CONTINUOUS PACKAGE FORMING MACHINE
Augustus H. Eberman and Hans A. Jensen, Madison,
Wis., assignors to Oscar Mayer & Co., Inc., Chicago,
Ill., a corporation of Illinois

Filed July 31, 1963, Ser. No. 299,000

22 Claims. (Cl. 53—112)

This invention relates generally to package forming machines and more particularly to a machine and components thereof by means of which hermetically sealed packages containing food products or other articles may be automatically and continuously formed. Specifically, this invention relates to new and improved packaging apparatus adapted for automatically and continuously forming packages from polyvinylidene chloride film or the like while making advantageous use of the unique supercooled properties of such film.

In co-pending applications, Serial No. 630,194, filed December 24, 1956, and Serial No. 61,993, filed October 11, 1960, and in U.S. Patent No. 3,083,106, various advantageous uses of polyvinylidene chloride film in its supercooled state have been disclosed. As is known to those skilled in the art, such film is formed from vinylidene chloride/vinyl chloride copolymers, such as "Saran," the film being extruded in the form of a thin sheet and immediately cooled as by advancing the same through a water bath maintained at a temperature of approximately 58° F. Merely by way of example, the film may be adequately supercooled by being passed into the water bath within about 0.1 to 3.0 seconds following its formation by extrusion, the time during which the sheet passes through the bath ranging from about 1 to 5 seconds. As the machine of this invention has been designed to use supercooled polyvinylidene chloride film and make use of properties of the latter, it is believed that a brief summary of the properties of such a film will aid in understanding and appreciating the invention.

Polyvinylidene chloride film in its supercooled state remains amorphous until a combination of time and temperature conditions causes crystallization. Substantial stretching of supercooled polyvinylidene chloride film is preferably avoided as its results in at least inducing crystallization, as evidenced by the crystals ultimately formed being at least substantially oriented, this type of induced crystallization eliminating the self-sealing properties of the supercooled film. While the film is maintained in its supercooled state without any substantial stretching occurring, the film may be sealed to itself merely by contact and without the necessity of applying film fusing heat or substantial pressure. The film is then crystallized as a result of time and/or temperature and, as evidence of full utilization of the supercooled properties, the film exhibits at least substantially random crystal distribution. Thus, as disclosed in the co-pending applications and patent referred to above, a pair of continuous sheets of supercooled polyvinylidene chloride film may receive spaced accumulations of product, i.e., articles to be packaged, therebetween with the articles and film surrounding the same being successively enclosed by cooperating and continuously moving die plates which in the course of their operation under controlled vacuumization conditions bring about automatic contact between the films around the articles to enclose completely the articles and automatically form hermetically sealed packages. The packages formed in this manner remain in longitudinally spaced-apart relation along the continuously moving and now sealed together films and the films are then crystallized to an adequate extent to at least substantially overcome the supercooled properties thereof after which the individual packages are automatically separated from the films.

2

Polyvinylidene chloride films used in the packaging operation briefly described above may vary in composition depending on the particular packaging properties required thereof. By way of example, laminates of polyvinylidene chloride film may be continuously prepared by forming separate films and combining them continuously prior to package formation. Oxygen barrier polyvinylidene chloride film may be formed from approximately 90% vinylidene chloride and 10% vinyl chloride whereas a film exhibiting a high degree of flexibility may be formed from approximately 68% vinylidene chloride and 32% vinyl chloride. With these two different types of film combined as a single laminate, the special individual properties cooperate in forming a package which exhibits the requisite flexibility to protect against damage during handling as well as the requisite oxygen impermeability for extending shelf life of food products, particularly meat products. Further and by way of example only, an oxygen barrier film may be formed with a thickness of about 0.001 of an inch whereas a flexible film may have a thickness of about 0.003 of an inch.

The polyvinylidene chloride film may be laminated with other films exhibiting desirable package forming and product protecting characteristics such as polyvinyl chloride film and polyvinyl acetate film. Various combinations of the various films may be made while utilizing the sealing characteristics of the polyvinylidene film in its supercooled state to form the package seal. The sealing area of the package may vary as to the type of seal formed. In a fully supercooled condition of the polyvinylidene chloride film, contacting of marginal portions of overlying sheets of film about articles to be packaged will result in a peripherally continuous fused seal. The seal can only be broken by destruction of the film, as in effect, the contacted film portions become fused to an extent that they form a unitary mass. By providing for controlled warming of the supercooled film to an extent that crystallization is at least partially induced results in the forming of a hermetic seal which can be broken by separating the sealed film areas by peeling.

It is a primary object of the present invention to provide a new and improved machine for continuously packaging articles in separate sealed packages formed of a film of the type described.

A further object of the invention is to provide in a machine of the type described means for successively and accurately depositing articles to be packaged on a conveyor which forms a part of the machine.

Still another object of the present invention is the provision of a machine of the type described including upper and lower die plate means traveling at the same speed for advancing sheets of packaging film so that one film overlies the other film at a packaging zone, the upper and lower die plate means being uniquely constructed in a new manner for sealing the films together around articles to be packaged which are supported on the lower film.

Another object of the present invention is the provision of a machine of the type described including upper and lower die plate means traveling at the same speed for advancing sheets of packaging film so that one film overlies the other film at a packaging zone, wherein the upper and lower die plate means are provided with novel cam actuated valve means for vacuumizing spaces between the films and for drawing the films into conformity with the contour of the articles to be packaged and for causing the films to be sealed together around the articles.

Even another object of the present invention is the provision of a machine of the type described including upper and lower die plate means traveling at the same speed for advancing films of the type described so that one film over-

lies the other film at a packaging zone, wherein the upper and lower die plate means are provided with first means for physically pressing the films together between articles to be packaged to form partially completed packages and second means for vacuumizing the partially completed packages and for drawing the films into conformity of the contour of the articles and for sealing marginal portions of the films to form completed packages.

A further object of the present invention is the provision of a machine of the type described including upper and lower die plate means traveling at the same speed for advancing sheets of the film of the type described so that one film overlies the other film at a packaging zone, wherein the upper die plate means is provided with improved means for forming a series of depressions in said one film before the latter reaches the packaging zone.

Another object of the present invention is the provision of the machine of the type described including upper and lower die plate means for advancing sheets of film of the type described so that one film overlies the other film at a packaging zone, wherein the upper die plate means are provided with improved means for holding said one film thereto while a series of depressions are formed in the film before the latter reaches the packaging zone.

Even another object of the present invention is the provision of a continuous package forming machine including upper and lower die plate means for advancing sheets of film of the type described so that one film overlies another narrower film at a packaging zone, which last mentioned film has articles to be packaged spaced thereon in longitudinal spaced-apart relation, the upper and lower die plates being provided with unique means for physically pressing the films together between the articles to form partially completed packages and then for vacuumizing the partially completed packages and for drawing marginal portions of the films together to form completed packages, the lower die plate means being provided with upstanding fence means for preventing premature sealing of marginal portions of the films during vacuumizing of said partially completed packages.

Still another object of the present invention is the provision of a machine of the type described including an upper endless series of die plates and a lower endless series of die plates for advancing sheets of packaging film so that one film overlies the other film at a packaging zone, wherein only one of the die plate means is driven and wherein separate means is provided on the upper and lower die plate means for interlocking engagement during movement of the upper and lower die plate means through said zone, whereby movement of the driven die plate means causes corresponding movement of the other die plate means.

A further object of the present invention is the provision of a machine of the type described including upper and lower die plate means for advancing sheets of film of the type described so that one film overlies the other film at a packaging zone, wherein the upper and lower die plate means include first and second means for physically pressing and vacuum drawing, respectively, said films together around articles to be packaged as the upper and lower die plate means pass through said zone, and wherein the lower die plate means include further means operated in part by said second means for temporarily holding by vacuum the other film on the lower die plate means after passage of the sealed together films through said zones, the films being held on the lower die plate means until the films have been severed around the completed packages formed therebetween.

A still further object of the present invention is the provision of a packaging machine of the type described including upper and lower die plate means for advancing films of the type described so that one film overlies the other film at a packaging zone, wherein the lower die plate means includes ejector plungers operable for lifting com-

pleted packages from the lower die plate means for transfer of the packages to delivery conveyor means.

Yet another object of the present invention is the provision in a machine of the type described new and improved means for severing completed packages from a film as the latter is being continuously advanced.

Another object of the present invention is the provision in a machine of the type described of unique cutting means for severing completed packages from package forming film, which means include a plurality of cutting wheels mounted above the film for simultaneous movement in a horizontal continuous path and for movement with the film at a velocity equal to the velocity of the latter, which continuous path corresponds to the peripheral shape of the packages, the cutting wheels being adapted to be brought into temporary contact with the film with the continuous path in registry with the periphery of one of the packages, whereby the cutting wheels sever the film at the periphery of the package as the film is being continuously advanced.

A further object of the present invention is to provide in a machine of the type described a unique cutting means for severing a packaging film around the periphery of the packages formed therein, the cutting means including feeler means engageable with the packages for bringing the cutting elements of the cutting means into operation upon contact of the feeler means with the package.

These and other objects and advantages of the present invention will become apparent from the following specification wherein like numerals refer to similar parts throughout.

In the drawings:

FIG. 1 is a side elevational view, in semi-diagrammatic form, of one embodiment of the continuous package forming machine of this invention;

FIG. 2 is a top plan view of the machine of FIG. 1 with certain parts of the machine being removed for better illustration of the invention;

FIG. 3 is a diagrammatic view showing the operation of the machine of this invention;

FIG. 4 is a vertical section taken through a sealed package formed by the machine of this invention;

FIG. 5 is a perspective view of the loading conveyor means for successively depositing articles to be packaged on the lower die plates of the machine;

FIG. 6 is a perspective view similar to FIG. 5 but showing the loading conveyor means unloaded and the lower die plates removed;

FIG. 7 is a close-up perspective view similar to FIG. 6 showing the stripper means which cooperate with the loading conveyor means for removal of articles from the latter for transfer to the lower die plates;

FIG. 8 is an enlarged fragmentary vertical section taken through one of the tray assemblies of the loading conveyor means;

FIG. 9 is a section taken along line 9—9 of FIG. 8;

FIG. 10 is an enlarged top plan view, with certain parts removed, showing certain of the stripper fingers engaging grooves in one of the trays of the loading conveyor means;

FIG. 11 is a section taken along the line 11—11 of FIG. 10;

FIG. 12 is a fragmentary perspective view taken at the packaging zone of the continuous package forming machine, the view being taken looking upstream from the right side of the machine;

FIG. 13 is an enlarged fragmentary perspective of the upper die plates and associated machine components;

FIG. 14 is a side elevational view, as seen from the left of the machine (looking downstream), of some parts of the machine comprising the packaging zone, the upper and lower die plates not being shown;

FIG. 14a is a side elevation of one of the upper cam tracks;

FIG. 14b is a side elevation of one of the upper cam tracks;

FIG. 15 is a section taken along line 15—15 of FIG. 14 showing the upper and lower die plates and associated supporting structure;

FIG. 16 is an enlarged fragmentary section taken along the line 16—16 of FIG. 14;

FIG. 17 is a perspective view of one of the upper die plates in partially completed form;

FIG. 18 is an enlarged section taken along line 18—18 of FIG. 17;

FIG. 19 is a fragmentary section taken along line 19—19 of FIG. 18, with certain supporting parts of the upper die plate not being shown;

FIG. 20 is an enlarged section taken along line 20—20 of FIG. 17;

FIG. 21 is an enlarged fragmentary section taken along the line 21—21 of FIG. 17;

FIG. 22 is an enlarged plan view of one of the upper die plates showing the face and cavity thereof;

FIG. 23 is a fragmentary view, partly in vertical section and partly in elevation, of an end portion of one of the upper die plates showing the articulated end plate structure therefor;

FIG. 24 is an enlarged end elevation of the structure shown in FIG. 23;

FIG. 25 is an enlarged fragmentary bottom view of the structure shown in FIG. 23;

FIG. 26 is a perspective view of one of the lower die plates with the ejector plunger forming a part thereof being slightly elevated from the face of the lower die plate;

FIG. 27 is an enlarged fragmentary top plan view of one of the lower die plates;

FIG. 28 is a fragmentary section taken along line 28—28 of FIG. 27;

FIG. 29 is a partial vertical section in semi-diagrammatic form, taken through the packaging zone of the machine of this invention showing the phase of operation of the upper and lower die plates when partially completed packages have been formed;

FIG. 30 is a section similar to FIG. 29 showing a later phase of operation with the die plates when completed packages have been formed;

FIG. 31 is a fragmentary perspective view of the downstream end of the continuous package forming machine primarily showing, the ejector plungers for removal of completed packages, the roller means for winding scrap film, and the cutting means for severing the sealed together films at the periphery of the packages formed therebetween;

FIG. 32 is a close-up perspective view of the cutting means in engagement with the sealed together films for cutting the films around one of the packages being advanced and also showing the scrap film wind-up means;

FIG. 33 is a perspective view of the downstream end of the machine with many parts of the machine being removed for primarily illustrating the mounting of the cutting means and the cam means for actuating the same;

FIG. 34 is a fragmentary side view of the downstream end of the machine, as seen from the left (looking downstream), with certain parts of the machine not being shown for primarily illustrating the cam means for actuating the cutting means and for illustrating the hydraulic ram for actuating the hydraulic motor which forms a part of the cutting means;

FIG. 35 is an enlarged fragmentary view, partially in vertical section and partially in elevation, looking downstream and taken through the cutting means of the machine;

FIG. 36 is a section taken along the line 36—36 of FIG. 35;

FIG. 37 is an enlarged vertical section taken through one of the lower die plates after the latter has passed beneath the cutting means;

FIG. 38 is a section similar to FIG. 37 showing a completed package being lifted from the face of one of

the lower die plates by means of the associated ejector plunger; and

FIG. 39 is a section taken along line 39—39 of FIG. 30.

Briefly and by way of introduction, the continuous package forming machine of this invention includes a lower endless series of die plates for receiving a polyvinylidene chloride film or the like from film extrusion and film super-cooling equipment and for advancing the film on the faces of the lower die plates in a horizontal linear path. In effect, the lower series of die plates act as a conveyor for advancing a film, hereinafter referred to as the lower film, through the entire machine. Means in the form of a separate loading conveyor are provided for successively and accurately depositing articles to be packaged in longitudinal spaced-apart relation on the advancing lower film so that the articles are positioned on the film in proper relation with the lower die plates. In the embodiment of the machine shown for purposes of illustration, the articles to be packaged are shown in the form of groups of bacon strips lying on each other in overlapping relation. Of course it is to be realized that the invention is not to be limited to the particular articles packaged.

An upper endless series of die plates are provided for receiving another film, hereinafter referred to as the upper film, of the type described from film extrusion and super-cooling equipment and for advancing the upper film in overlying relation with the lower film at a packaging zone. The upper die plate means are in communication with a source of vacuum and include unique cam operated valve

means for forming a series of depressions in the upper film before the latter reaches the packaging zone. The accumulations of the products or articles to be packaged which are longitudinally spaced-apart on the lower film are successively received in the depressions in the upper film as the films are advanced through the packaging zone by the upper and lower die plates, which upper and lower die plates cooperate to form article enclosing vacuum chambers. The upper and lower die plates have respective flange portions extending transversely of the film for physically pressing the films together between the articles to be packaged thereby sealing the films together to form partially completed packages, i.e., marginal portions of the films remain unsealed at this phase of operation. The upper and lower die plates include novel cam actuated valve means for communicating the source of vacuum via the lower die plates to the spaces defined by the partially completed packages for vacuumizing the same. The upper and lower die plates include further cam actuated valve means including vent means for vacuum pressing the films

into conformity with the contour of the articles to be packaged and for vacuum pressing marginal portions of the films together for sealing of the same thereby forming completed packages.

The completed packages are uncovered by the upper die plates as the packages leave the packaging zone and are conveyed by the lower die plates through a crystallization zone which includes suitable film heating means, such as an infra-red heating unit, which adequately raises the temperature of the sealed together films to an extent that crystallization is sufficiently advanced to overcome the supercooled properties of the films.

The packages are continuously advanced from the crystallization zone to a cutting zone which includes novel cutting means for severing the films on the lower die plates. The cutting means includes a plurality of depending cutting wheels moving in an endless path and moving with the film, during a portion of its length of travel, for severing the films around the periphery of the packages for separating the latter from the films.

The lower die plates include novel means for holding by vacuum the lower film to the faces of the lower die plates as the latter pass through the cutting zone for preventing movement of the films as they are being severed by the cutting means. Roller means are provided for

winding the scrap film which remains after the completed packages have been severed from the films.

The lower die plates include ejector plungers which are disposed in the faces of the lower die plates beneath the packages formed thereon. The plungers are adapted to be lifted from the faces of the die plates by cam means after the lower die plates have passed through the cutting zone for transfer of the completed packages to a delivery conveyor, for example.

Referring now to the drawings and in particular FIG. 1, the continuous package forming machine of this invention primarily includes, in serial relation progressing along the direction of travel of the films or in a "downstream" direction, a loading zone 10, a packaging zone 12, a crystallization zone 14, a cutting zone 16 and a scrap film wind-up and package delivery zone 18. The rectangular object diagrammatically illustrated in FIG. 1 in zone 14 represents an electrical junction box for controlling electrical components of the machine, such as the drive motors thereof. The machine will be described proceeding from loading zone 10 to wind-up and package delivery zone 18. Before describing the equipment which comprises loading zone 10, the lower die plates of the machine will be briefly described because of the interrelation of the loading zone equipment with the lower die plates.

The lower die plate means include an endless series of die plates 20 each being supported for movement in an endless path by rollers guided in trackways which form a part of the supporting structure of the continuous package forming machine. Lower die plates 20 are articulated on a pair of endless chains 21 (FIG. 5) driven by suitable motor means, such as an electric motor 22 illustrated in FIG. 1. Referring momentarily to FIGS. 33 and 34, motor 22 drives a gear box having a sprocket wheel 22a for driving a chain 23 (shown in broken lines) which is trained over a sprocket wheel 23a and rotates a further sprocket wheel 24 fixed on a cross shaft 24a. Shaft 24a is rotatably mounted in the supporting structure of the machine and includes suitable sprocket portions 24b at one end thereof for driving a pair of juxtaposed chains 25, which chains are trained over a double sprocket wheel 26 fixedly mounted on a cross-shaft 27. Shaft 27 is rotatably mounted in the supporting structure of the machine and carries sprocket wheels 27a in driving engagement with lower die plate chains 21.

Referring back to FIG. 1, the lower die plates are adapted to receive a continuous sheet of polyvinylidene chloride film 24 on their faces and advance the film in a horizontal linear path through the machine. Film 24 is received by the lower die plates in its supercooled state, which film is formed by suitable film extrusion and supercooling means such as those disclosed in the aforementioned co-pending applications and patent. Suitable hold-down roller means 28, diagrammatically shown in FIG. 1, are provided for insuring smooth and co-extensive contact between film 24 and the faces of the lower die plates, which faces are planar and define a substantially continuous horizontal moving surface for advancing the lower film. In effect, the endless series of lower die plates act as a conveyor for advancing lower film 24.

As it will become apparent herein when describing the operation of the equipment forming the packaging zone of the machine of this invention, the articles to be packaged must be accurately spaced or located on the lower film. The machine of this invention includes means in the form of a unique loading conveyor which operated in an inter-related manner with movement of the lower die plates for successively depositing articles on the film being continuously advanced on the lower die plates, the loading conveyor principally comprising loading zone 10.

The loading conveyor generally designated 29, includes means for continuously advancing an endless series of trays 30 in a horizontal course which passes over the lower film obliquely thereto. The loading conveyor includes suitable supporting structure for mounting horizontally

disposed, endwise confronting upper and lower guide tracks 31 and 32, respectively, (FIG. 8). The shape of the guide tracks and their disposition relative to the lower die plates is illustrated in FIG. 2.

5 The loading conveyor includes a plurality of identical equally spaced-apart tray support members 33 each of which includes upper and lower pairs of integral ear portions 34 mounting upper rollers 35 and lower rollers 36 for being received in respective guide tracks 31 and 32. Both of the lower pair of ears 34 of each support member 33 mount pulleys 37 on their upper surfaces, the pulleys being rotatably mounted on bushing members 38. At least one of the bushing members 38 cooperates with a depending member 39 attached to the underside of the 10 corresponding upper ear 34 for connecting each member 33 with an endless chain 40. Members 38 and 39 have co-axial bores for receiving a pin 41, which pin extends through one of the links in chain 40. Pulleys 37 have annular recesses 37a adapted to receive guide tracks 43 15 (FIG. 6) which extend in a horizontal plane between the upper and lower guide tracks of the loading conveyor.

It will be apparent that support members 33 are moved in an endless horizontal path by corresponding movement of chain 40. The chain is driven by a sprocket wheel 25 having teeth thereon adapted for meshing engagement with the links of the chain, the sprocket wheel being driven by a vertically extending shaft 46 (FIGS. 1 and 6). Shaft 46 is operatively connected at the lower end thereof with a gear box 47, the gears of which are operated by a sprocket wheel 48 driven by a chain 49, which chain is driven by sprocket wheel 50 fixedly mounted in a cross shaft 51 supporting sprocket wheels (not shown) which are in meshing engagement with chains 21 of the lower die plates. In other words, chain 40 is moved in 20 timed relation with chains 21 for timed movement of trays 30 with the lower die plates.

As best seen in FIG. 8, a wheel 53 is mounted on shaft 46 for rotation with sprocket wheel 45. Wheel 53 engages the annular grooves in pulleys 37 for assisting in 25 guiding support members 33 as they move around the corners of their course defined by the guide tracks of the loading conveyor. In other words, wheel 53 forms a continuation of guide tracks 43 at one bend in the course of movement of the support members. It will be understood that a wheel similar to 53 is rotatably mounted at 30 each bend of the course of movement of members 33.

Each tray support member 33 has a pair of parallel, vertically extending open ended bores 55 for freely receiving a pair of rods 56. The rods are mounted for 35 axial reciprocating movement in bores 55 by a number of bearing assemblies 57. Rods 56 have reduced-in-diameter threaded portions at the lower ends thereof for being received in apparatus 58 in an arm member 60. Arm 60 is secured to the lower ends of rods 56 by nuts 61 which hold the arm against the annular shoulders defined on the rods by the reduced-in-diameter threaded portions of the same. Each arm member 60 has one of the trays supported therefrom.

The upper ends of each pair of rods 56 extend above 40 the upper end of the corresponding support member and have a head member 63 secured thereto. It will be understood that head member 63 is secured to the upper ends of both rods of each support member for movement in unison with the rods. Head member 63 has a depending portion with a pin 64 depending therefrom, which pin is adapted to be received in a central vertically extending bore 65 provided in support member 33. A coil spring 66 is contained in bore 65, which spring has the upper portion thereof encircling pin 64 and abutting the depending portion of the head member for constantly urging the same upwardly, thereby constantly urging both rods and the tray secured thereto upwardly relative to the support member. Head member 63 is adapted to be cammed downwardly against the force of spring 66 for 45 50 55 60 65 70 75

moving trays 30 into close proximity with film 24 being advanced on the lower die plates for transfer of articles on the trays to the lower film.

Each head member 63 has cam rollers 67 and 68 extending from opposite sides thereof. As best seen in FIG. 5, cam roller 68 is adapted to be engaged by a cam track 69 as support member 33 begins to travel along the portion of its course over the advancing lower film. Cam track 69 may be moved upwardly (to a position where it will not cam the rollers 68 downwardly) by means of an actuating arm assembly 70, which assembly is supported on a vertically extending plate 71 which is in turn supported from the supporting structure of the loading conveyor. A locking arm assembly 72 is provided for locking assembly 70 in place when cam track 69 is moved down to its operative position for engagement with cam rollers 68. Cam rollers 68 of the head members ride on a continuous horizontal track (not shown), which track is cut-away in the upper surface thereof along its portion extending over the lower film, thereby allowing the head members to be moved downwardly by cam track 69 for camming of trays 30 into close proximity with the advancing lower film 24.

Referring now in particular to FIGS. 6, 7 and 10, each tray 30 will be seen to be generally rectangular in shape having a plurality of diagonally disposed, spaced-apart, grooves 75 defining parallel ribs 76 therebetween. Tray 30 is mounted in a horizontal plane from the lower end of arm 60 by a plurality of threaded fasteners 77, the tray being mounted with respect to support 33 such that grooves 75 are parallel with the course of movement of the tray as it passes obliquely over the lower film being advanced on the lower die plates. The ribs extending to the trailing rear edge of the tray have raised portions at their ends defining co-planar faces 79 which lie in a vertical plane which is perpendicular to the path of movement of the lower film when the trays pass over the latter along the oblique course of the trays. In effect, vertical co-planar faces 79 define abutment means or stop means extending along one trailing edge of the tray.

Conveyor stripper means, generally designated 82, are mounted in alignment with the oblique course of travel of the conveyor loader trays for cooperating with the abutment means on the trays to remove articles from the trays and accurately deposit them onto the moving lower film. The stripper means includes a horizontally disposed stepped bar 83 suspended from a plate 84, which plate is secured to the lower end of a vertically extending plate 85, plate 85 being slidably mounted to one side of plate 71 for vertical reciprocating movement. Cam track 69 is supported from plate 85; actuating arm 70 moves cam track 69 and bar 83 vertically in unison. Bar 83 may be secured to plate 84 by means of threaded fasteners 86, for example. The stepped bar extends over the right side of the lower die plates, as viewed looking downstream, and extends in a direction parallel with the direction of movement of the lower die plates.

The inner stepped side of bar 83, i.e., the side of bar 83, i.e., the side facing the lower die plates, has a plurality of evenly spaced-apart steps defined by side wall portions 87 and front wall portions 88. A depending stripper finger 90 is pivotally secured from each side wall portion 87 by means of a pin 91, which pin has a threaded shank portion threadingly engageable with a complementary threaded bore in bar 83. The mounting of bar 83 and the spacing of the fingers are such that the latter are in alignment with respective grooves in the trays. It will be noted that the total number of fingers exceeds the total number of tray grooves by one. The extra finger, which is located at the downstream end of bar 83, is adapted to have inclined side 92 of each tray pass along one side of this finger during movement of the trays. It will be understood that the lower ends of the fingers pass through grooves 75, relatively speaking, during movement of the

trays beneath the conveyor stripper means. Each finger has a vertical face 93 which lies in a vertical plane parallel with the direction of movement of the lower film, all faces 93 of the fingers being co-planar.

The fingers are pivotally mounted on bar 83 in a resilient manner to prevent jamming of the loading conveyor in the event the fingers are not in proper alignment with the grooves or in the event articles on the trays are for some reason prevented from being removed from the trays upon engagement with the fingers. As best seen in FIG. 11, each finger 90 is pivotally mounted at the upper end thereof, as by means of a pin 95, to a horizontally extending bar 96 which extends diagonally across bar 83 and has a lug plate 97 secured to the other end thereof. The outer stepped side of the bar includes a plurality of steps defined by side wall portions 98 and rear wall portions 99, and bar 83 includes a threaded bore 100 in each rear wall portion for threadingly receiving one end of a pin 101. A coil spring 102 circles each pin 101, which spring has one end thereof abutting rear wall portion 99 and the other end thereof abutting one face of lug 97 for normally urging the same into engagement with nuts 103 threadingly engaged on threaded stud portion 101a of pin 101. It should be apparent that if the lower ends of the fingers 90 engage ribs on the tray or articles jammed on the tray, the fingers will rotate, in a clockwise direction as viewed in FIG. 11, thereby allowing passage of the tray or articles for preventing damage to the loading conveyor.

As seen in FIG. 10, a pair of spring clips 105 are secured, as by means of screws 106, to the upstanding portions of a pair of ribs 76 on each tray. These clips have their free ends bent upwardly slightly for engagement with the trailing rear edge portion of an article supported on the trays for holding the article securely on the former. As noted in FIG. 6, the two ribs nearest the corner of each tray which is secured to arm 60 also have upstanding portions 108 at their other ends, i.e., the ends at one of the leading sides of the tray, which upstanding portions each have vertical faces 109 which are contained in a vertical plane parallel with the direction of movement of the lower film. Upstanding portions 108 and faces 109 are substantially identical to upstanding portions 78 and faces 79. A spring clip 110, similar in construction to spring clips 105, is suitably secured to one of the upstanding portions 108, the clip 110 being adapted for engagement with a leading side edge portion of an article supported on tray 30.

The operation of the loading conveyor forming a part of the continuous package forming machine is as follows:

For purposes of illustration, it will be assumed that slices of bacon are to be deposited on the lower film in longitudinal spaced-apart accumulations for being packaged in separate sealed packages by the continuous package forming machine. As seen in FIGS. 4 and 5, bacon slices 112 are stacked in overlapping relation on a rectangular base member 113 which may be made of cardboard or other suitable material. The base member has an integral upstanding flap 114 which may bear suitable indicia. Each base member 113 carrying the articles or bacon strips to be packaged will be hereinafter referred to as the product.

The products may be delivered to the moving loading conveyor 29 by one or more delivery conveyors 116 (shown in phantom lines in FIG. 2) and loaded on trays 30 by hand, for example. Each product is located on one of the trays so that a rear and side edge of base member 113 abuts tray faces 79 and 109, respectively. This is a relatively easy operation to accomplish by hand as it is only necessary to slide or push the products onto the trays toward the corners thereof secured to arms 60. With the products positioned on the trays as just described, the various spring clips 105 and 110 overlie rear and side marginal portions of the product for holding the same in place.

The trays move in the direction of arrows as indicated in FIG. 2. As mentioned above, the trays are moved in timed relation with movement of the lower die plates which support lower film 24, and the trays move in a horizontal course which has a portion passing over the lower film at an oblique angle thereto. The timing between movement of the loading conveyor and the lower die plates is such that the trays move along their oblique course over the lower die plates at a velocity which has a vectorial component with a velocity equal to the velocity of the lower die plates. The reason for this inter-relationship of the velocities of the loading conveyor and lower die plates will become apparent hereinbelow.

As each tray 30 reaches a position along its oblique course over the lower die plates, it is cammed downwardly into close parallel relation with the advancing lower film by reason of the engagement of cam roller 68 with cam track 69. As mentioned above, tray faces 79 are contained in a vertical plane which is perpendicular to the path of movement of the lower film, and tray faces 109 are contained in a vertical plane which is parallel to the direction of movement of the lower film. Accordingly, as each tray passes along its oblique course over the moving lower film, the product supported on each tray will be positioned so that its trailing rear edge extends perpendicular to the direction of movement of lower film and its leading side edge extends parallel to the direction of movement of the lower film. As each tray moves across the film in close proximity with the same, the leading side edge of the product is simultaneously engaged by faces 93 of the first three stripper fingers of the conveyor stripper means. The number of fingers initially engaged will depend upon, among other things, the number of fingers provided on the conveyor stripper means and the size of the products supported on the trays. Engagement of this leading side edge of the product with the fingers fixes the lateral position of the product with respect to the lower film as the fingers prevent further movement of the product in a direction parallel with the direction of movement of the trays along their oblique course.

As the trays move along their oblique course, the product engaged by the stripper fingers commences movement in a direction parallel with movement of the lower film at the instant the product is contacted by the fingers. By virtue of the timed movement between the loading conveyor and the lower die plates, the products begin this movement the instant they are properly longitudinally positioned over the lower film. This movement of the product, which is relative to the tray on which it is still supported, is brought about by the combined action of the stripper fingers and the abutment faces 79 engaging the trailing rear edge of the product. As faces 93 of the stripper fingers are co-planar in a vertical plane which is parallel to the direction of movement of the lower film, these fingers engaging the leading side edge of the product permit movement of the latter only in a direction parallel with movement of the lower film. The engagement of tray faces 79 with the trailing rear edge of the product causes the product to move in a direction parallel to the direction of the lower film as the leading side edge of the product slides along finger faces 93. During this movement of the product, the associated tray slides laterally with respect to the product by reason of movement of the tray along its oblique course. Or in other words, the trailing rear edge of the product slides along tray faces 79 transversely of the lower film. Stated another way, it may be said that the trays slide diagonally or obliquely from beneath the products after the products come into engagement with faces 93 of the stripper fingers.

As the trays move from beneath the products, the latter drop onto the moving lower film. Since the trays move along their oblique course with a velocity which has a vectorial component having a velocity equal to the

velocity of the lower film, there is no relative movement between the products and the lower film after the products have been engaged by the stripper fingers. Therefore, the products are smoothly and accurately transferred to the advancing lower film in proper longitudinally spaced-apart relation thereon. It will be understood of course that the timing between movement of the loading conveyor and the lower die plates is such that each product is deposited on the lower film in its proper position over one of the lower die plates. The lateral position of the products on the lower film is a function of positioning of the stripper fingers, and the longitudinal position of the products is a function of relative tray and lower die plate spacing and velocity.

As each tray is cammed downwardly by cam track 69 into close proximity with lower film 24, the distance between the upper surface of the tray and the lower film is kept at a minimum thereby reducing the likelihood of misalignment of the products as they are transferred from trays 30 to the lower film. After the trays have passed over the advancing lower film, cam rollers 68 roll off cam track 69 allowing the trays to be urged upwardly by springs 66 to their normal position for being reloaded from one of the delivery conveyors 116.

The lower die plates continuously advance lower film 24 having products longitudinally spaced-apart thereon to packaging zone 12. The packaging zone is defined by an upper endless series of articulated die plates cooperating with the lower die plates for first sealing an upper film 30 with the lower film between the products to be packaged to form partially completed packages, for then vacuumizing the partially completed packages and finally sealing marginal portions of the films together to form completed packages.

Referring now to FIGS. 13 and 17 through 25, each upper die plate, generally designated 118, will be seen to include an elongated upper body member 119 and a lower generally rectangular body member 120. As all upper die plates are of identical construction, only one upper die plate will be described in detail. Upper member 119, which has a planar bottom 121, opposite vertical sides 122, and a top portion defined by inclined sides 123 and a top surface 124, includes a pair of transversely extending parallel bars 125 suitably secured to bottom 121 adjacent opposite end of the latter. Body 119 includes a blind bore or passageway 127 extending for substantially the entire length thereof and opening at one end of member 119 at an opening 127a (FIG. 17). The upper body member includes a second blind bore or passageway 128 extending parallel with bore 127 and similarly opening at one end of member 119 at an opening 128a. As will be explained hereinafter, passageway 127 is placed in communication with a source of vacuum; bore 128 is not utilized in the embodiment of the package forming machine shown for purposes of illustration but may be placed in communication with a source of gas, such as nitrogen.

The upper body member of upper die plate 118 includes a central cam actuated valve assembly, generally designated 130, and further cam actuated valve assemblies, generally designated 131 through 134, equally spaced-apart in pairs on opposite sides of the central valve assembly.

Referring now to FIGS. 17 and 21, cam actuated valve assembly 130 will be seen to include an inclined bore 136 opening into inclined side 123 at a cutaway portion 136a. Bore 136 has a co-axial, reduced-in-diameter extension 136b opening into an inclined bore 137, which last mentioned bore opens at one end thereof at side 123 and communicates at the other end thereof with a vertically disposed blind bore 138. Blind bore 138 opens at the lower end thereof at bottom 121 of the upper body member. A bushing 139 mounted in bore 136 mounts a valve member 140 for axial reciprocating movement in

bore 136, which valve member has an enlarged face 141 adapted to seat on the annular shoulder at the juncture of bore 136 and its extension 136b. Valve member 140 is constantly urged in the position illustrated in FIG. 21, i.e., with face 141 in flush contact with the annular shoulder in bore 136, by a coil spring 142. Spring 142 encircles member 140 and has one end thereof abutting an O-ring 143 held against the inner end of bushing 139 and has the other end thereof abutting the annular surface defined by face member 141. Bore 137 is closed at the outer end thereof by a plug indicated at 144. A vertical bore 145 opens at the outer end thereof at top surface 124 and is in communication at the other end thereof with bore 136 thereby opening the latter to atmosphere.

Valve member 140 has a notch 140a at the outer end thereof, which notch is adapted to receive the tip of an arm 146 integral with a rocker arm 147. Rocker arm 147 is pivotally mounted on the upper end of a lug 148, which lug is rigidly secured to upper body member 119 adjacent cutaway portion 136a. A cam roller 149 is rotatably mounted on the upper end of the rocker arm by a nut and bolt assembly 150. It should be apparent that downward movement of the cam roller, as by means of its engagement with a cam track, results in clockwise rotation of the rocker arm, as viewed in FIG. 21, for lifting of valve face 141 from the valve seat in bore 136 thereby communicating bore 138 with the atmosphere through bore 145.

Referring to FIG. 20, cam actuated valve assembly 131 will be seen to include an inclined bore 152 opening at one end thereof in one inclined side 123 at a cutaway portion 152a. Bore 152 includes a co-axial, reduced-in-diameter extension 152b, which extension opens at the inner end thereof into passageway 127. A vertically extending bore 153 opens at the outer end thereof at the bottom surface 121 of the upper body member and communicates at the upper end thereof with bore 152. Cam actuated valve assembly 131 includes a rocker arm and valve arrangement (not illustrated in FIG. 20) identical to that of cam actuated valve assembly 130. The rocker arm and the cam roller of valve assembly 131 are identified as 155 and 156, respectively (FIG. 17). It should be apparent that downward movement of cam roller 156 opens valve assembly 131 for communicating bore 153 with blind passageway 127.

It will be understood that cam actuated valve assembly 133 is opposite hand but otherwise identical in construction to valve assembly 131 for communicating a further bore 153 (not shown) with passageway 127. The rocker arm and cam roller of valve assembly 133 are respectively designated 157 and 158.

Cam actuated valve assembly 132 is illustrated in FIGS. 17-19. This valve assembly includes an inclined bore 160 opening at one inclined body side 123 at a cutaway portion 160a. Bore 160 includes a co-axial, reduced-in-diameter extension 160b, which extension communicates at the inner end thereof with bore 127. A blind bore 161 extending centrally and axially of body member 119 and plugged at the outer end thereof at 162 intersects bore 160 at the portion of the latter just short of the annular shoulder defined by bore 160 and extension 160b. Blind bore 161 communicates with a vertically extending bore 163, bore 163 being co-axial and in communication with a vertical port 164 in bar 125. Port 164 opens at the outer end thereof at the bottom face of bar 125 at an enlarged annular portion 164a, the enlarged annular portion being adapted to receive an annular sealing gasket 165 (FIG. 29) for a purpose to be referred to hereinafter. It will be understood that cam actuated assembly 132 includes a rocker arm and valve member arrangement identical to those valve assemblies 130 and 131, the rocker arm and cam roller of valve assembly 132 being designated 166 and 167, respectively. It will be apparent

that downward movement of cam roller 167 opens valve assembly 132 for communicating port 164 with blind passageway 127.

Cam actuated valve assembly 134 is opposite hand but otherwise identical in all respects to cam actuated valve assembly 132. The rocker arm and cam roller of valve assembly 134 are respectively designated 168 and 169. Manifestly, opening of valve assembly 134 communicates passageway 127 with its associated port 164.

It will be noted from FIG. 17, that upper die plate 118 is provided with a pair of further cam actuated valve assemblies generally designated 170 and 171. Valve assemblies 170 and 171 are identical but opposite versions of valve assemblies 132 and 134, respectively. Cam actuated valve assemblies 170 and 171, which include inclined bores 172 (FIG. 19) are provided for communicating blind bore 128 with vertical port 164 in bars 125. As valve assemblies 170, 171 are not used in the embodiment of the continuous package forming machine shown for purposes of illustration, they will not be further referred to herein.

Lower body member 120 of upper die plate 118, as best seen in FIGS. 17, 20 and 22, includes a generally rectangular cavity 174 bordered by transversely extending, i.e., transversely of the direction of movement of the die plates, marginal flange portions 175 and opposite side marginal portions 176. A pair of parallel, longitudinally extending grooves 177 (FIG. 16) are provided in the face of cavity 174 adjacent opposite ends of the latter. Grooves 177 are provided to accommodate upstanding fences on the lower die plates, the purpose of which fences will be referred to hereinafter.

A continuous groove 178 extends around the periphery of the cavity 174 for receiving a sealing gasket 179. Lower body member 120 includes a plurality of inclined small bores 181 at opposite ends thereof, each of which bores opens at one end thereof at a top surface 182 of the body member and opens at the other end thereof at marginal portion 176. As seen in FIG. 16, bore 181 has a reduced-in-diameter portion 181a adapted to receive a needle 182. A further inclined bore 183 is provided with each bore 181, which bore 183 communicates with reduced-in-diameter bore portion 181a for threadingly receiving a threaded fastener 184, such as a set screw, for frictionally engaging needle 182 for holding the same in its proper axial position in bore portion 181a. The needles are positioned for projecting slightly into longitudinally extending grooves 185 which are provided adjacent opposite ends of lower body member 120 in flange portions 176 thereof. The purpose of the needles will be referred to hereinbelow.

Lower body member 120 is secured to bottom 121 of the upper body member with opposite ends of the lower body member being disposed between longitudinally extending bars 125. The upper and lower body members of the upper die plates are secured together by means of threaded fasteners 187 (FIG. 29), which fasteners are adapted to be received in bores 188 in member 120 registering with threaded bores 189 in member 119. The lower body member 120 includes a central port 190 opening at one end thereof into cavity 174 and opening at the other end thereof at top surface 182 of member 120, which port registers with bore 138 when the upper and lower body members are secured together. The lower body member also includes a pair of ports 191 similarly opening into the cavity and top surface 182 of the lower body member, which ports are adapted for respective registration with bores 153 of the upper body member when both body members of the upper die plate are bolted together.

The upper die plates are completed by mounting the secured together upper and lower body members 119 and 120, respectively, between end plate assemblies best seen in FIGS. 23-25. The end plate assembly at only one end of one of the upper die plate is illustrated; it will be un-

derstood that identical construction is provided at the opposite end of the upper die plate.

A pair of transversely extending cross bars 192 extend on opposite sides of the upper body member and are secured adjacent their opposite ends to bars 125 by threaded fasteners 192a, which fasteners are threadingly engageable in threaded bores 125a (FIG. 17) in the bars 125 registering with bores (not shown) provided in cross bars 192.

Corresponding ends of cross bars 192 are resiliently secured to an end plate 193 by means of a pair of threaded fasteners 194 which are threadingly engaged in bores 195 provided in the end plates. Springs 196 encircle shank portions of fasteners 194 and engage head portions of the fasteners and the upper surface of the bars for constantly urging the latter into engagement with the flat top surfaces 193a of the end plates. Bars 192 are provided with enlarged bores 197 for freely receiving shank portions of fasteners 194 for permitting movement of the bars axially of the threaded fasteners. It will be realized that the upper and lower body members of the upper die plate, which are secured together and secured to cross bars 192, are in effect resiliently mounted on end plates 193 and adapted for limited movement relative thereto axially of fasteners 194. As will become apparent below, this resilient mounting permits the body members of the upper die plate to move slightly relative to the end plates for accommodating the planar surface of the mating lower die plate for properly cooperating with the latter for forming a product enclosing vacuum chamber.

End plate 193 includes a suitable recess 193b in the outer side thereof for mounting a center plate 200, which center plate supports an upper roller 201. End plate 193 includes, intermediate the ends thereof, a vertically extending bore 202, which bore opens at one end thereof at the bottom surface of the end plate. A dowel pin 203 is securely mounted in bore 202 and extends a short distance beyond the bottom surface of the end plate. The purpose of the dowel pin will be referred to below.

End plate 193 is bifurcated at one end thereof for forming ear portions 193c and 193d having co-axial apertures 205 for receiving a pin 206 mounting a roller 207 at one end of the latter. The other end of plate 193 is cut away for forming a lug portion 193e having a bore 208 for receiving pin 206 held in the ear portions of the complementary shaped end of plate 193 of the adjacent upper die plate. The upper die plates are articulated together for traveling in an endless path in a vertical plane by the complementary engagement of the lugs and ears of the end plates pivotally secured to each other by pins 206.

A sub-end plate 210 is secured to the end of upper body member 119 having openings 127a and 128a therein by means of a plurality of threaded fasteners 211. The sub-end plate includes a pair of threaded bores 212 and 213 registering with openings 127a and 128a, respectively. A plug 214 (FIGS. 13 and 24) is secured in bore 213 for plugging blind bore 128 in the upper body member of the upper die plate as this blind bore is not utilized in the embodiment of the invention shown for purposes of illustration. Opening 212 is adapted for threading engagement with a fitting 215 (FIG. 13) for securing a vacuum hose 216 to each upper die plate.

As seen in FIGS. 12 through 15, the articulated upper die plates are mounted between opposite guide track assemblies 220 for movement in an endless path in a vertical plane. Each guide track assembly 220 includes an upper horizontal track 221 defining an upper horizontal run, and each guide track assembly includes a lower horizontal track 222 defining a lower horizontal run. As best seen in FIG. 15, when the upper die plates travel along their upper horizontal run they are supported on tracks 221 by rollers 207. When the upper die plates pass along their lower horizontal run they are urged into contact with the lower die plates by engagement of rollers 207 with the underside of guide tracks 222. The upper and

lower guide tracks are joined at their corresponding ends by semi-circular guide track assemblies 223 and 224. Semi-circular track assemblies 223 and 224 include suitable track means (not shown) engageable with rollers 207 at opposite ends of the upper die plates for guiding the latter in semi-circular paths between their horizontal run portions of movement.

As noted in FIG. 14, each lower track 222 includes raised, short, arcuate tracks 225, 226 at opposite ends thereof. Tracks 225 engage rollers 201 for lifting the upper die plates slightly just before they come into mating engagement with the lower die plates. This slight lifting of the upper die plates prevents the leading transverse edge of body 120 from striking the faces of the lower die plates. By this construction the upper die plates are brought into overlying parallel relation with the lower die plates and then forced downwardly into engagement with the latter by the action of rollers 207 on the underside of tracks 222. Tracks 226 engage rollers 201 for lifting the upper die plates from the lower die plates just before the upper die plates commence their upper arcuate path. This lifting of the upper die plates prevents their trailing transverse edges from striking the faces of the lower die plates during separation of the die plates. The upper die plates are driven by movement of the lower die plates in a manner to be described hereinbelow.

As seen in FIG. 12, flexible vacuum lines 216 connect each upper die plate with a rotary valve assembly 227, which assembly is mounted on a cross shaft 228 having one end thereof suitably journaled in a vertically disposed plate 229. Plate 229 is secured to one end of an arm 230 which has the other end thereof secured to the supporting structure of the continuous package forming machine. Valve assembly 227 is rotated by shaft 228 for moving vacuum lines 216 along with movement of the upper die plates. Valve assembly 227 includes suitable means, known to those skilled in the art, for constantly communicating a source of vacuum (not shown) with each vacuum line 216 via a vacuum conduit 231.

Cross shaft 228 is rotated in timed relation with movement of the lower die plates by means of a sprocket wheel 232 (FIG. 14) secured to the end of the cross shaft opposite the end thereof bearing the rotary valve assembly. Sprocket wheel 232 is driven by a chain 233 (indicated in phantom lines) which is in turn driven from a sprocket wheel 234 rotatably mounted on a gear box assembly 235. Gear box assembly 235 is operated by a chain 236 which extends to a suitable sprocket wheel on gear box 47.

Now referring to FIGS. 26 through 30, each lower die plate 20 will be seen to include a one-piece casting 238 having integral depending lugs 239 at the corners thereof. As all lower die plates are of identical construction, only one lower die plate will be described in detail. A roller 240 is rotatably mounted in an aperture (not shown) in each lug 239. One opposite pair of rollers is held on the lugs by nuts 241. The other opposite pair of rollers is held on the lugs by bushings 242, which bushings include bores 242a for receiving pins 21a of chains 21 for connecting each lower die plate to the chains. Casting 238 includes integral lug portions 243 at opposite ends thereof, the lug portions being provided with dowel receiving openings 244, which openings open at the upper surface of the lug portions at beveled portions 244a. The upper or top surface of the casting, which is generally planar, includes a rectangular, planar, recessed portion 245 defining opposite raised side marginal portions 246. Side portions 246 are co-planar with the upper surfaces of lug portions 243.

Rectangular recessed portion 245 includes a centrally disposed circular recess 247, which recess includes an annular step or ridge 248 extending around the periphery thereof. A disc-like ejector plunger 249 is adapted to be received in circular recess 247 and rest on annular step 248. The upper surface of plunger 249 is co-planar with side portions 246 when the plunger is resting on step 248.

The diameter of plunger 249 is slightly less than the diameter of the circular recess above step 248 for defining a thin annular space between the periphery of the disc and the periphery of the circular recess. The ejector plunger rests on annular step 248 in a manner so that the just mentioned annular thin space communicates with the space defined by the underside of the plunger and the base of the circular recess. This may be accomplished by providing upper surface of step 248 with a slightly uneven contour or by providing suitable grooves or the like in step 248. 10

As seen in FIGS. 29, 30 and 39, a stem 251 normal to the ejector plunger has one end thereof secured to the same, the stem being adapted for axial reciprocal movement in a suitable bearing 252 supported in an opening 15 formed in casting 238 and a depending casting hub portion 238a. A right-angle bracket 253 has the shorter leg thereof secured to the underside of casting 238 adjacent hub portion 238a, and the bracket has the longer leg thereof extending parallel with the axis of stem 251 and in a vertical plane extending longitudinally of the continuous package forming machine. Bracket 253 includes a vertically extending slot 254 in the depending or longer leg thereof for slidably receiving a guide 256, which guide has a pair of oppositely disposed grooves 257 adapted to engage the sides of slot 254 for permitting sliding movement of the guide along the length of the slot. Guide 256 has an integral lug 256a in engagement with an annular recess 251a provided on the free end of the stem. It should be apparent that reciprocating movement of guide 256 in slot 254 causes corresponding reciprocating movement of stem 251 for movement of the ejector plunger into and out of circular recess 247. Guide 256 has a cam roller 258 mounted thereto, which cam roller is adapted to be engaged by a longitudinally extending cam track 259 (FIG. 34) for lifting of the ejector plungers in sequence at an appropriate time during the travel of the lower die plates along the machine. The purpose and operation of the ejector plungers will be referred to hereinbelow. 20

Referring back to FIGS. 27 and 28, the planar recessed portion 245 of each lower die plate will be seen to include a pair of parallel, longitudinally extending grooves 261 adjacent opposite end portions of recess 245. Each groove 261 includes a transversely disposed portion 261a intermediate the length thereof and extending inwardly of the lower die plate. Each groove 261 has a long narrow slot 263 extending along the length thereof and extending beyond opposite ends of the groove for receiving a longitudinally extending fence member 264. Fences 264 extend slightly above planar surfaces 246 of the lower die plate. The purpose of the fences will be explained below. 30

A flat rectangular plate 266 (FIGS. 29 and 30), preferably made of spring steel, is detachably supported in lower die plate recess 245 by suitable means and is co-extensive with the latter with its upper surface being coplanar with marginal flange portions 246 of the lower die plate. Plate 266 is provided with a central circular opening 267 concentric with recess 247 and having a diameter equal to the latter for accommodating plunger 249. Plate 266 is also provided with a pair of parallel, longitudinally extending, rectangular shaped openings 268 for freely receiving the upstanding fence plates 264. As noted in FIGS. 29 and 30, openings 268 are wide enough to provide open spaces on opposite sides of the fence plates. 50

Referring now to FIGS. 29 and 30, each lower die plate will be seen to include three cam actuated valve assemblies generally designated 270, 271 and 272.

Cam actuated valve assembly 270 includes a bore 273 in the casting of the lower die plate, which bore opens at one end thereof at the bottom of the lower die plate and communicates at the other end thereof with a co-axial, reduced-in-diameter bore 274. Bore 274 opens into groove portion 261a in recess 245 of the lower die plate. A bush- 70

ing 275 is mounted in the outer end of bore 273. A valve member 277 is mounted for reciprocal movement in the bushing, and the valve member has a circular face 278 adapted to seat on the annular shoulder defined by bores 273 and 274. Valve member 277 is constantly urged upwardly for sealing engagement of face 278 with the annular shoulder in bore 273 by means of a coil spring 279. The coil spring encircles valve member 274 and has one end thereof abutting an O-ring 275a which is held against the inner end of bushing 275 and the other end thereof abutting the annular surface defined by face 278 on the valve member. Valve member 277 is reciprocated in the bushing by a rocker arm 280 pivotally mounted on the lug 281, which lug is suitably secured to the underside of the casting of the lower die plate. Rocker arm 280 supports a cam roller 282. Details of the rocker arm, the mounting lug and the cam roller are not shown; it will be understood that these parts are constructed in a manner similar to the rocker arm, supporting lug and cam roller rocker arm, supporting lug and cam roller of the upper die plate valve assemblies.

A transversely extending passageway 283 has one end thereof opening exteriorly of casting 238 and has the other end thereof communicating with bore 273. Casting 283 includes a port or passageway 285 opening in flange portion 246 of the lower die plates at one end thereof and communicating at the other end thereof with passageway 283. As noted in FIGS. 29 and 30, passageway 283 intersects bore 294 provided in lug portion 243 of the casting forming the lower die plate. Passageway 283 is plugged along the length thereof, as indicated at 287, between bore 244 and port 285. It will be understood that upward movement of cam roller 282 results in downward movement of valve member 277 for communicating grooves 261, 261a with port 285. 35

Cam actuated valve assembly 271 includes a bore 289 opening at one end thereof at the bottom of the lower die plate and communicating at the other end thereof with a co-axial reduced-in-diameter bore 290. Bore 290 opens into the base or bottom of circular recess 247. A bushing 291 is mounted in the outer end of bore 289 and slidably receives a valve member 292 for axial reciprocal movement in bore 289. Valve member 292 includes a circular face 293 on the inner end thereof for seating on the annular shoulder defined by bores 289 and 290. A coil spring 294 encircles valve member 292 adjacent the face thereof for constantly urging the face into sealing engagement with the annular shoulder defined by bores 289 and 290. The coil spring has one end thereof abutting the O-ring adjacent the bushing and the other end thereof abutting the annular surface defined by circular valve face 293. The outer end of the valve member is engaged by one end of a rocker arm 296, which rocker arm is pivotally mounted on a lug 297 secured to the underside of the lower die plate. A cam roller 298 is rotatably mounted on one end of the rocker arm so that upward movement of the cam roller, as by engagement with a cam track, results in downward movement of the valve member thereby unseating face 293 from the annular shoulder defined by bores 289 and 290. It will be understood that actuation of cam actuated valve 271 in the manner just described results in communication between port 290 and a transversely extending passageway 299, the latter passageway opening into bore 289. 50

Cam actuated valve assembly 272, which includes rocker arm 300 and cam roller 301, is an opposite hand but otherwise identical version of cam actuated valve assembly 270. Accordingly, valve assembly 272 will not be described in detail. It need only be said that bore 273 associated with valve assembly 272 communicates with transversely extending passageway 299. As valve member 277 has a diameter considerably smaller than the diameter of bore 273, it defines an annular chamber within bore 273 which is always in communication with passageways 283 and 299. Accordingly, passageway 299 is al- 60 65 75

ways in communication with port 285 associated with cam actuated valve assembly 272.

Referring again to FIGS. 29 and 30, sleeves 302 are secured in the enlarged bore portions 244a provided in lugs 243 of the lower die plates. Sleeves 302 have beveled faces 302a in the outer ends thereof for assisting in guiding dowel pins 203 into the sleeves. The sleeves and dowel pins cooperate in a manner to affect movement of the upper die plates upon movement of the lower die plates in a manner to be referred to hereinbelow.

Referring now especially to FIGS. 1, 3, 12 and 14, an upper continuous sheet of polyvinylidene chloride film 305 is received from suitable extrusion and supercooling equipment (not shown) on an upper conveyor for guiding the upper film in a horizontal downstream path terminating in packaging zone 12 over the upper die plates. Upper film 305 is trained downwardly from conveyor 306 and around a hold-down roller 307 (FIG. 14) for covering relation with the faces of the moving upper die plates. The manner of driving the upper die plates in their endless path over the lower die plates for cooperation with the latter will now be described.

As mentioned above, the endless series of lower die plates 20 are secured to endless chains 21 driven by electric motor 22 illustrated in FIG. 1. The lower die plates then move in a continuous horizontal planar path along their upper run through the continuous packaging machine. The lower die plates are guided in their endless path by engagement of rollers 240 in opposite endless lower trackways 250 forming a part of the supporting structure of the machine. As described above, the upper die plates are guided for movement in an endless path above the lower die plates by engagement of rollers 207 with the underside of the upper guide track assemblies 220. The upper guide track assemblies are arranged on the supporting structure of the continuous packaging machine so that as the upper die plates move along their lower run portion through packaging zone 12 marginal flange portions of the upper and lower die plates come into substantial co-extensive contact as illustrated in FIGS. 29 through 30. It will be recalled that the upper and lower body members 119 and 120, respectively, and cross bars 192 of the upper die plates are resiliently mounted for limited movement relative to the upper die plate end plate assemblies by means of springs 196 and bolts 194. The various parts are arranged so that marginal flange portions of the upper die plates are pressed on marginal flange portions of the lower die plates during movement of the upper die plates along their lower horizontal run portion. As the upper die plates pass from guide tracks 223 and come into contact with the lower die plates, the upper die plates, i.e., body members 119 and 120 and cross bars 192 are resiliently pressed into engagement with the lower die plates by tracks 222, rollers 207, springs 196, etc. This construction insures substantial co-extensive contact of marginal flange portions of the upper and lower die plates notwithstanding manufacturing and assembly tolerances in the upper and lower die plates and in their supporting structure and guide tracks, etc., thereby adapting the upper and lower die plates to cooperate or seal at their marginal portions for forming article enclosing vacuum chambers.

As marginal flange portions of the upper and lower die plates come into contact in the manner just described, dowel pins 203 extending from the upper die plates are received in sleeves 302 held in lug portions 243 of the lower die plates. This engagement of the dowel pins in the sleeves provides the drive means for the upper die plates. In other words, the upper die plates are freely supported for endless movement in upper guide track means 220 and are driven by movement of the lower die plates. This construction obviates the need for separate drive means for the upper die plates and the necessary timing means for insuring synchronized or timed move-

ment of the upper die plates relative to the lower die plates.

Now referring back to FIG. 14, side marginal portions of the upper die plates, as they move along their upper horizontal run portion, receive upper film 305 as it passes around hold-down roller 307, and the upper die plates advance the upper film in a horizontal path in an upstream direction before bringing the latter into overlying relation with lower film 24 being advanced by the lower die plates, which lower film has articles to be packed longitudinally spaced-apart thereon as described above.

The upper film, which has a width substantially the same as the width of the lower body members 120 of the upper die plates, has its marginal portions secured to side marginal flange portions of body members 120 by means of needles 182, which needles project slightly into longitudinally extending grooves 185 in members 120. Marginal portions of film 305 are pressed into grooves 185 and pierced by needles 182 by means of a pair of rollers 308 mounted one on each side of the upper die plates along their upper run portion.

Each roller 308 (FIG. 16) includes an annular recess 308a around the periphery thereof for receiving a continuous resilient or deformable ring 309, which ring rolls in one of the advancing grooves 185 for pressing the margin of film 305 into the groove to be pierced by needles 182. This secure engagement of margins of the upper film with marginal flange portions of body members 120 of the upper die plate prevents wrinkling or dislocating of the upper film as it is drawn into cavities 174 of the upper die plates. Each roller 308 is rotatably mounted on a pin 309a which pin has one end thereof secured in an arm. Arm 310 is pivotally mounted on an upstanding member 311 supporting conveyor 306, and arm 310 is suitably clamped by means (not shown) for holding roller 308 into engagement with side marginal portions of the upper die plates.

As noted in FIG. 14, a roller assembly 313 is mounted above the upper horizontal run portion of the upper die plates. The assembly includes an oil absorbent roller 314 which engages the faces of the upper die plates as they pass beneath the roller for being coated with a suitable release agent to prevent sticking of the upper film to the upper die plate sealing gasket after the upper film passes through the packaging zone.

The upper die plates having upper film 305 in covering relation with their faces as described above, are advanced by movement of the lower die plates and guided through guide tracks 224 for bringing the upper film into overlying relation with the advancing lower film. Cam track means are provided for actuating the various valve assemblies on the upper and lower die plates for forming a series of depressions in the upper film to receive the articles to be packaged for vacuumizing the packages when they are in partially completed form, and for sealing marginal portions of the upper and lower films together to form separate completed packages. The various cam track means will now be described.

As best seen in FIGS. 13, 14, 15, 29 and 30, the valve actuating means for the upper die plates include a plurality of parallel, longitudinally extending, spaced-apart cam tracks designated 315 through 319. These linear cam tracks extend for the length of packaging zone 12. Opposite ends of cam track 315 are secured to depending brackets 321 (FIG. 15), which brackets are secured to the lower flanges of cantilever support members 322. Cantilever members 322 are supported in parallel spaced-apart relation transversely of the continuous package forming machine by upright members 323 (FIG. 14) which comprise a part of the supporting structure of the machine.

Corresponding opposite ends of cam tracks 316 and 317 are secured to depending brackets 325, which brackets are secured to the underside of respective cantilever members 322. Cam tracks 318 and 319 have correspond-

ing opposite ends secured to brackets 326 which depend from respective cantilever members 322 near the free ends of the latter. As noted in FIG. 15, two additional upper cam tracks, 328 and 329 are supported from respective brackets 321 and 326. Cam tracks 328 and 329 are provided for actuation of cam actuated valve assemblies 171 and 170, respectively. Cam tracks 315, 316, 317, 318 and 319 are laterally positioned in the packaging zone for respective engagement with cam rollers 169, 158, 149, 156 and 167 of the various valve assemblies associated with the upper die plates.

As seen in FIGS. 13 and 14, a horizontally disposed cam bar 332 extends longitudinally in an upstream direction from upstream cantilever member 322. Suitably secured, as by threaded fasteners 333, to one side of bar 332 is a circular cam member 334. Member 334 lies in a vertical plane extending longitudinally of the machine, and member 334 is laterally positioned for engagement with cam roller 156 of valve assembly 131.

Cam track 319 has a continuous, horizontal, planar cam surface 319a illustrated in FIG. 14. Cam track 315 is identical in shape with cam track 319.

Cam track 318 (FIG. 14a) has a lower, horizontal, planar cam face 318a connecting with a stepped-up, horizontal, planar cam face 318b. Upper cam track 316 is identical in shape with cam track 318.

Cam track 317 has an upstream, horizontal, planar cam face 317a joining with a downstream, horizontal, stepped-down, planar cam face 317b (FIG. 14b). Cam track 317 is slightly longer than the other upper cam tracks. The upstream end of all the upper cam tracks lie in a horizontal line which extends transversely of the direction of movement of the die plates.

The lower cam tracks, i.e., the cam tracks provided for actuation of the various valve assemblies on the lower die plates, include parallel, spaced-apart, longitudinally extending cam tracks, 336, 337 and 338. As seen in FIG. 15, cam tracks 336 and 337 have corresponding opposite ends secured to upstanding members 339, which upstanding members are secured to transversely extending support members 340 comprising a part of the supporting structure of the continuous package forming machine. Cam track 338 has its opposite ends secured to upstanding members 341 which are mounted on respective transversely extending members 340. Cam tracks 336, 337 and 338 are of identical length and shape and include continuous, horizontal, planar cam faces 336a, 337a and 338a, respectively. Lower cam track 338 is shown in elevation in FIG. 14.

The cam actuated valve assemblies of the upper and lower die plates are sequentially actuated by the various cam tracks just described for drawing the upper film into the cavities of the upper die plates, for vacuumizing the packages when they are in partially completed form, and for sealing marginal portions of the upper and lower films together to form separate, completed, sealed packages. Six phases of die plate operation occur during the formation of each sealed package; these phases are indicated by letters A through F in FIG. 14. The lines extending to these encircled letters indicate the location of the upper and/or lower die plates as these phases of operation occur.

The upper die plates, which have upper film 305 in covering relation with their phases and pierced by needles 182, are guided by guide tracks 224 from their upper horizontal run portion downwardly to their lower horizontal run portion. As each upper die portion is guided downwardly by guide tracks 224, cam roller 156 of valve assembly 131 is engaged by cam member 334 as the upper die plate reaches station A. This engagement of cam roller 156 with cam member 334 results in communicating port 191 associated with valve assembly 131 with blind passageway 127, which blind passageway is constantly in communication with a source of vacuum by

means of one of the flexible lines 216 and rotary valve 227, etc. This actuation of valve assembly 131 at station A results in vacuumizing the space defined by cavity 174 and upper film 305. As the face of the upper film is open to atmosphere at station A, i.e., it has not yet come into contact with the face of one of the lower die plates, the upper film is drawn into cavity 174 along substantially the shape illustrated in FIG. 29. An effective seal is formed between the upper film and the cavity adjacent the periphery of the latter by sealing gasket 179 provided on each of the upper die plates. The upper film need not be completely drawn into the cavities in the upper die plates; it need only be drawn into these cavities for forming depressions in the upper film of a size sufficient to accommodate the spaced accumulations of articles to be packaged which are being advanced on the lower film.

Cam roller 156 remains in engagement with the periphery of cam member 334 until the associated upper die plate reaches station B. At this station valve assembly 131 is allowed to close for closing port 191 associated with valve assembly 131 thereby maintaining the vacuum in the space defined by cavity 174 and the upper film for maintaining the depression formed in the latter. It will be apparent that as the upper die plates are advanced between stations A and B, a series of product receiving depressions are formed in the upper film.

Stations C through F define the packaging zone proper. Just before the upper and lower die plates reach station C, each upper die plate and its mating or associated lower die plate come together in cooperative relation, i.e., respective marginal flange portions of mating upper and lower die plates come into substantial co-extensive contact, with the depressions in the upper die plate receiving the product positioned on the corresponding lower die plate. When the upper and lower die plates come together or cooperate in the manner just described, the upper and lower die plates form product or article enclosing vacuum chambers by virtue of their contact at marginal flange portions. Also, when the upper and lower die plates are in the cooperative relationship just described, dowel pins 203 are respectively received in sleeves 302 and ports 164 in the upper die plate are in respective registry with ports 285 in the corresponding lower die plate. Effective seals between ports 164 and ports 285 are insured by gaskets 165.

As each upper die plate and its mating or associated lower die plate reach station C, valve assemblies 131 through 134 and valve assemblies 270 through 272 are simultaneously actuated. That is, cam rollers, 156, 167, 158, 169, 282, 298 and 301 are simultaneously engaged by cam faces 318a, 319a, 316a, 315a, 338a, 337a and 336a, respectively. Accordingly, at station C ports 191 associated with valve assemblies 131 and 133 are placed in communication with vacuumized blind passageway 127 for again vacuumizing the space between cavity 174 and upper film 305. Vacuumizing this space holds the upper film in at least partial spaced relation with respect to the product during vacuumizing of the space between the upper and lower films in a manner to be described below.

As best seen in FIG. 29, actuation of valve assembly 132, 134, 270 and 272 at station C results in communication between vacuumized passageway 127 and ports 274 via registering ports 164, 285, etc. In other words, ports 274 in the lower die plates are now in communication with the source of vacuum for vacuumizing the packages to be formed as the upper and lower die plates pass through the packaging zone.

At this time it should be noted that as respective transversely extending flange portions of the upper and lower die plates come into confronting relation during movement of the upper and lower die plates through the packaging zone, the upper and lower films are physically pressed together at these transversely extending flange portions for being sealed together between the products. That is, the upper and lower films are sealed together

along transversely extending lines which are evenly spaced-apart longitudinally of the advancing films. As noted in FIGS. 29 and 30, the upper film is of a width substantially the same as the width of lower body member 120 of the upper die plates. However, lower film 24 is somewhat narrower in width. Marginal portions of the lower film extend to the inner edges of openings 268 in plates 266 thereby insuring clearance spaces between margins of the lower film and upstanding fences 264. It will be noted then that marginal portions of the upper and lower films are not brought into contact by virtue of the mating or cooperating engagement of the upper and lower die plate flange portions.

It will be recalled that ports 274 in each lower die plate are placed in communication with the source of vacuum as the lower die plate and its associated upper die plate pass station C. This results in vacuumizing the product enclosing space between the films via grooves 261, grooves 261a, ports 274, etc. Grooves 261 communicate with this product enclosing space through openings 268 in plate 266 and through the spaces between fences 264 and margins of lower film 24. During passage of mating upper and lower die plates from station C to station D the upper and lower films are brought together in what is termed partial package forming relation. That is, the upper and lower films are sealed together along transverse lines intermediate the products, but the films remain unsealed at marginal portions thereof thereby allowing vacuumizing of the product enclosing spaces between the films.

As mentioned above, valve assembly 271 of each lower die plate is actuated when the lower die plate reaches station C. This results in communicating port 290 with passageway 291 and passageway 283 thereby placing port 290 in communication with the source of vacuum. As port 290 opens into the space defined by the underside of plunger 249 and the base of recess 247, this space becomes vacuumized. As mentioned above, plunger 249 and recess 247 are configured to provide a thin annular space between the periphery of the plunger and the periphery of the recess, which thin annular space is in communication with the space defined by the underside of the plunger and the base of the recess. Therefore, the source of vacuum is applied to this thin annular space at the periphery of the plunger thereby applying the source of vacuum to the underside of the lower film at this thin annular space. This serves as a unique means for holding the lower film to plate 266 of the lower die plates for preventing movement of the lower film relative to the die plates during trimming or severing of the sealed together films at a package cutting zone to be referred to hereinbelow.

As each upper die plate and its mating or associated lower die plate reaches station D in the packaging zone, valve assemblies, 131 and 133 are closed and valve assembly 130 is substantially simultaneously opened. That is, cam rollers 156, 158 and 149 substantially simultaneously engage cam tracks 318b, 316b, and 317b, respectively. The remaining valve assemblies of the upper and lower die plates remain open. Accordingly, at station D the space between cavity 174 and the upper film is closed from the source of vacuum and opened to atmosphere through bore 145 in the upper die plates. When this occurs, the upper film is pressed into contact with the products for conforming to the contour of the latter and marginal portions of the upper film are pressed or drawn into contact with margins of the lower film by reason of the vacuum applied to the product enclosing spaces between the upper and lower films. Upper film 305 assumes the shape illustrated in FIG. 30 shortly after it passes station D. It should be noted that fences 264 associated with each lower die plate prevent premature sealing of marginal portions of the upper and lower films during vacuumizing of the product enclosing spaces between the upper and lower films and during drawing of

the upper film into conformity with the contour of the products.

The upper film is pressed into conformity with the contour of the products and marginal portions of the upper film are drawn into contact with margins of the lower film before the time the cooperating upper and lower die plates reach station E, i.e., completed packages are formed when the die plates reach station E. As each upper die plate and its mating lower die plate pass station F, valve assemblies 131 through 134 and valve assemblies 270 through 272 are simultaneously closed. This occurs shortly before separation of the upper and lower die plates for preventing communication of the source of vacuum with atmosphere through ports 164 in the upper die plates. Closing of valve assembly 271 in the lower die plates traps the vacuum formed at the underside of the lower film between the periphery of the ejector plungers and the circular recesses in the lower die plates. This vacuum holds the sealed together films on the lower die plates after their passage through the packaging zone.

Valve assembly 130 remains open until just slightly before separation of the upper and lower die plates. This valve assembly is opened after cam roller 149 passes beyond the downstream end of cam face 317b, which cam face extends a short distance downstream beyond the downstream ends of the remaining cam tracks.

After the upper and lower die plates separate, the completed packages are exposed on the lower die plates 30 and advanced by the latter through the remaining portion 35 of the machine. The upper die plates are removed from their cooperative relation with the bottom die plates following package forming and are then returned along their upper run for continuous re-use. The lower die plates continue to advance the now sealed together films defining separate completed packages. The sealed together films are now advanced by the lower die plates through crystallization zone 14. This zone includes suitable film heating means (not shown), such as an infra-red heating unit 40 which raises the temperature of the sealed together films to an extent that crystallization is sufficiently advanced to overcome adequately the supercooled properties of the films.

Referring now to FIGS. 31 through 36, a cutting or trimming mechanism, generally designated 345, forming a part of the continuous packaging machine primarily includes a head mechanism 346 suspended from a transversely extending cross member 347, which member has opposite ends thereof suitably secured to a pair of parallel, vertical members 348. A plurality of vertically extending shafts 350 are rotatably mounted at upper ends thereof, as by bearing assemblies 351, in cross member 347. One shaft 350 is illustrated in FIG. 35, which shaft has a coaxial upwardly extending extension 350a keyed to a coupler 352, which coupler is suitably secured to a depending drive shaft 353 of a hydraulic motor 354. Only one of the vertically extending shafts 350, which are positioned in a generally rectangular path in a horizontal plane, is coupled to a hydraulic motor 354. A generally rectangular plate 356 is mounted in parallel, vertical spaced-apart relation beneath a depending rectangular portion 347a of member 347 by means of a plurality of suitable brackets 357.

Head mechanism 346 further includes a lower generally rectangular plate 359 having spaced-apart bearing assemblies 360 in engagement with the lower ends of shafts 350. A further horizontally extending plate 362 is mounted in parallel vertically spaced-apart relation above plate 359 by means of a plurality of spacers 363 and associated pins 364. Plates 356, 362, 359 and plate portion 347a have identical peripheral shapes and are in vertical alignment. The peripheral surfaces of these members define guide tracks for guiding a plurality of equally spaced-apart cutting members 366 in an endless horizontal path around

the head mechanism. Plates 356 and 362 include respective co-axial openings for freely receiving shafts 350.

A horizontally disposed plate 368 is mounted in the head mechanism for vertical reciprocal movement relative to the latter. Plate 368 is mounted in the head mechanism in the manner just described by means of a plurality of bushings 369 secured to the upper surface of the plate and slidably engageable with respective depending pins 370, which pins are secured to the underside of plate 356. Plate 368 includes a plurality of openings 371 for freely receiving pins 370, each of which pins has a ring-like seat 372 secured to the lower or free end thereof for abutting the underside of plate 368. The lowermost position of plate 368 relative to the head mechanism is fixed by abutting engagement of the underside of the plate with the upper surfaces of seats 372. Plate 368 includes a number of openings 373 for freely receiving shafts 350.

As best seen in FIGS. 35 and 36, plate 368 has a centrally disposed opening 374 for freely receiving a vertically extending rod 375. A block 376 is secured to the underside of plate 368 and includes a central opening 377 co-axial with opening 374. A sear 378 is pivotally mounted in a suitable slot in block 376 by a pin 379 for swinging movement in a vertical plane, which sear has a foot 378a adapted for engagement with the upper surface of an annular flange 375a formed on the lower end of rod 375. A rod 380 is pivotally mounted by a pin 381 to sear 378, which rod extends downwardly through respective openings 362a and 359a in plates 362 and 359. A clevis 383 is secured to the lower end of rod 380 and has a bar 384 pivotally mounted in the bifurcated portion thereof by a pin 385. One end of bar 384 is pivotally mounted by a pin 386 from a depending lug 387 secured to the underside of plate 359 adjacent the central enlarged opening therein. A pair of co-axial package engaging rollers 388 are mounted to the other end of bar 384 one on each side thereof by a pin 389.

As noted in FIG. 36, a vertically extending bar 390 has the lower end thereof pivotally mounted to sear 378 at pin 381. The upper end of bar 390 is operatively associated with a counter 391, of known construction, for counting packages formed by the continuous packaging machine. The actuation of this counter will be referred to hereinbelow. Openings 356a and 347a are provided in respective members 356 and 347 for freely accommodating vertically extending bar 390.

All cutting wheel assemblies 366 are of identical construction. Each assembly 366 includes a vertically extending outer plate 392 having three, horizontally extending, vertically spaced-apart guide blocks 393, 394 and 395 secured thereto. Secured to the upper end of each plate 392 is an upper block 396. Block 396 has upper, inner and lower rollers 398, 399 and 400, respectively, suitably secured thereto. Roller 398 is adapted for rolling movement in an endless guide trackway 401 formed around the periphery of depending portion 347a cross member 347. Rollers 399 and 400 are adapted for rolling movement on the upper marginal surface and vertical edge, respectively, of plate 356.

Each guide block 395 mounts an upper roller 403, an inner roller 404 and a lower roller 405. Upper roller 403 and inner roller 404 are adapted for respective rolling engagement with the vertical edge and lower marginal portion of plate 362. Lower rollers 405 are adapted for rolling engagement in endless guide trackways 406 formed on the periphery of lowermost plate 359. It should be apparent that each plate 392 is adapted for movement in an endless path in a horizontal plane by rolling engagement of the various rollers just described on the various plates making up the head mechanism.

Guide blocks 393 and 394 of each cutting assembly 366 include co-axial bores at the inner ends thereof for receiving sleeves 408 and 409. Sleeves 408 and 409 rotatably mount a vertically extending rod 410 which receives at its opposite ends opposed pins 411 and 412, which

pins form a part of respective endless chains 413 and 414. Chains 413 and 414 are driven by respective sprocket wheels 416 and 417, which sprocket wheels are mounted in vertical spaced-apart relation on shafts 350.

As only one shaft 350 is driven by hydraulic motor 354, the remaining sprockets act as idler sprockets for guiding the chains in their endless path around the head mechanism. It should be apparent that actuation of motor 354 results in movement of cutting assemblies 366 in an endless horizontal path around the head mechanism.

Guide blocks 393, 394 and 395 include aligned openings for freely receiving a lower vertically extending plate 420 for vertical reciprocal movement of the latter along the inside surface of plate 392. Each plate 420 includes a vertically extending rectangular slot 421, the upper end of which slot is adapted to engage a stop member 422 secured to plate 392 and extending inwardly thereof. A spring 423, diagrammatically shown in FIG. 35, constantly urges plate 420 downwardly. A second stop 425 secured to plate 392 and extending inwardly thereof is adapted to be abutted by the upper end of plate 420 for limiting upward movement of the latter relative to plate 392.

Each plate 420 includes a further vertically extending rectangular opening 427 (FIG. 32) in the lower end thereof for receiving a guide block 428 for vertical reciprocal movement relative to plate 420. It will be understood that block 428 has vertically extending grooves at opposite sides thereof for slidably receiving corresponding sides of opening 427 to permit sliding movement of the guide block relative to plate 420. A knurled nut 428a suitably mounted to plate 420 in the upper end of opening 427 has a threaded shank portion 429 (FIG. 35) threadingly engageable in an upstanding bore in a hub member 430. Hub member 430 supports a horizontally extending axle 431 rotatably mounting a cutting wheel 432. The horizontally extending sleeve portion of the hub supporting pin 431 is externally threaded for receiving a pair of lock nuts 433. The innermost lock nut is adapted for frictional engagement with the inner side of plate 420. Knurled nut 428a provides means for adjusting the vertical position of cutting wheel 432 relative to plate 420, and lock nuts 433 provide means for locking hub 430 to plate 420 after the former has been adjusted. It will be apparent that cutting wheels 432 are moved in an endless horizontal path upon actuation of motor 354. The various roller engaging plates of the head mechanism are shaped so that this path corresponds with the peripheral shape of the packages formed between the advancing upper and lower films.

Each plate 420 has secured thereto near its upper end an inwardly extending rod 435 mounting a roller 436 at the free end thereof. Rollers 436 are adapted for rolling engagement around the upper marginal surface of plate 368.

A collar 438 is secured to the upper end of rod 375 which collar includes an annular recess 438a having a roller 439 received therein, the roller being mounted to one end of a crank arm 440, the other end of which crank arm is mounted to one end of a cross shaft 441. Cross shaft 441 is journaled in suitable openings in a pair of upright members 442 and 443 mounted on plate 347. A second crank arm 444 is secured to the outer end of cross shaft 441, and crank arm 444 has a vertically extending threaded bore in the free end thereof for threading engagement with shank 445 of a knurled knob 446. Lower end of shank 445 is adapted for abutting engagement with the upper end of one of a pair of posts 448, which posts are fixed in respective sleeves 449 secured to the inner upper portions of a pair of upright members 450. Crank arms 440 and 444 are configured on opposite ends of cross shaft 441 so that upward movement of shank 445, as by its engagement of the upper end of the associated post 448, causes upward movement of rod 375 in the head mechanism.

The head mechanism is supported by separate structures at opposite sides of the machine, the structures being

opposite hand but otherwise identical versions of each other. As best seen in FIG. 35, each vertical member 348 of the head mechanism has a pair of aligned bearing assemblies 451 and 452 secured in vertical spaced-apart relation on the outer surface thereof, which bearing assemblies are adapted for reciprocal sliding movement on the corresponding post 448. Bearing assembly 452 is shown in cross section in FIG. 35 and includes ball bearing elements 453. A right angle bracket 454 extends outwardly from the upper end of vertical member 348 around bearing assembly 451, which bracket has an opening 454a in the horizontal leg thereof for freely receiving a shaft 455. Shaft 455 is supported at the lower end thereof by a block 456 secured to the outer surface of the associated upright member 450. A coil spring 457 encircles shaft 455 and has one end thereof abutting the upper surface of block 456 and has the other end thereof abutting the underside of bracket 454 around the opening therein. It will be apparent that springs 457 constantly urge the head mechanism upwardly.

Each vertical member 348 has a cam roller 459 at the lower end thereof. Cam rollers 459 are engaged in respective inner cam tracks 460 formed in the inner faces of a pair of cam wheels 461, the cam wheels being mounted on shaft 24a for rotation with the same. Continuous cam tracks 460 are substantially circular and are eccentrically mounted with respect to the center of cam wheels 461. It will be apparent that rotation of cam wheels 461 produces vertical reciprocation of the head mechanism by reason of the rolling engagement of cam wheels 459 in cam tracks 460, the head mechanism being adapted for reciprocation in a vertical plane by reason of the sliding engagement of bearing assemblies 451 and 452 on posts 448 as explained above.

As best seen in FIGS. 33 and 34, each upright member 450 is in the form of an inverted, generally Y-shaped member having horizontally disposed leg portions 450a. A pair of aligned bearing assemblies 463 are secured to the inside vertical surfaces of leg portions 450a adjacent the outer ends thereof. Bearing assemblies 463, which may be of identical construction to bearing assembly 452 illustrated in FIG. 35, slidably receive co-axial, longitudinally extending rods 464 and 465. Forward rods 464 are suitably secured to upright members 465 forming a part of the supporting structure of the machine, and rearward rods 465 are suitably secured to upright members 466 also forming a part of the supporting structure of the continuous packaging machine. It will be understood that both upright members 450 are adapted for horizontal reciprocal movement between upright members 465 and 466. Each upright member 450 includes a cutaway portion 450b in the lower edge thereof for accommodating shaft 24a during horizontal reciprocation of the upright members.

Each upright member 450 has a cam roller 468 mounted on the inner vertical surface thereof adjacent cut-out portion 450b, which roller is adapted for rolling movement in a continuous substantially circular cam track 469 formed in the outer surface of cam wheel 461 eccentric with respect to the center of the latter. It should be apparent that rotation of cam wheels 461 produce horizontal reciprocal movement of the uprights by reason of the rolling engagement of cam rollers 468 in cam tracks 469.

Means are provided for automatically energizing hydraulic motor 354 in timed relation with movement of the head mechanism, which head mechanism is simultaneously and continuously reciprocated in horizontal and vertical planes by reason of cam rollers 459 and 468 rolling in respective cam tracks 460 and 469 of the cam wheels. Such means include a hydraulic ram 470 (FIG. 34) having one end thereof pivotally mounted by a pin 471 to a depending plate 472 forming a part of the supporting structure of the continuous packaging machine. A pair of hydraulic lines 473 and 474 (FIGS. 31 and 34), suitably connected with one way check valves and a reservoir

(not shown), communicate ram 470 on opposite sides of the piston therein with hydraulic motor 354. The hydraulic ram includes a piston rod 475 having the outer end thereof pivotally mounted by a pin 476 in one of a series of apertures in a wheel 477. The holes in wheel 477 are formed therein at varying radii for adjusting the length of the stroke of piston rod 475 upon rotation of wheel 477. Wheel 477 is mounted on a shaft 478, which shaft is secured to wheel 23a and is thereby driven by the main drive motor 22. Hydraulic ram 470 is actuated in timed relation with movement of the lower die plates and the combined movements of the head mechanism, all of which components are driven from a common drive means, viz., motor 22. The operation of cutting means 345 is as follows:

The continuously moving lower die plates advance the sealed together films having completed packages formed in longitudinally spaced-apart relation therebetween to cutting zone 16. The continuously moving cam wheels 461 cause continuous vertical reciprocation of the head mechanism relative to the uprights and cause continuous horizontal reciprocation of the uprights relative to the supporting structure of the machine. The angular velocity of the cam and the interrelation of the various parts are such that the uprights are advanced in a forward or downstream direction with a velocity equal to the velocity of the lower die plates. The various parts of the cutting means are designed so that the uprights begin their forward stroke when the horizontal endless path defined by the path of movement of cutting wheels 342 is in registry with the periphery of one of the completed packages 476 being advanced on the lower die plates. Simultaneous with the beginning of the forward stroke of the uprights, the head mechanism begins its downward stroke relative to the uprights. After the head mechanism moves nearly its entire distance downwardly, the lower end of shank 445 of knurled nut 446 abuts the top of the associated fixed post 448. This contact of shank 445 with the associated post 448 causes upward movement of rod 375 relative to the downwardly traveling head mechanism by reason of cross shaft 441 and the crank arms at opposite ends of the latter.

As best seen in FIG. 36, upward movement of rod 375 relative to the downwardly traveling head mechanism causes corresponding upward relative movement of plate 368 by reason of the engagement of sear 378 with flange 375a. Relative upward movement of plate 368 causes corresponding upward relative sliding movement of plates 420 by reason of the engagement of cam rollers 436 on the upper marginal portion of plate 368.

However, just prior to the time rod 375 would commence its upward relative movement for causing upward movement of plates 420 (and accordingly cutting wheels 432) relative to the downwardly traveling head mechanism, rollers 388 are engaged by the leading inclined surface of one of the completed packages 476. This engagement of rollers with the package causes clockwise rotation of sear 378 (as seen in FIG. 36) thereby moving sear foot portion 378a clear of the upper annular surface on flange 375a. Accordingly, the upward relative movement of rod 375 no longer causes corresponding upward relative movement of plate 368, as the rod is now adapted for free sliding movement relative to plate 368 and block member 376 secured to the underside thereof. Accordingly, plates 420 are not moved upwardly relative to plates 392 and are forced downwardly by means of the springs 423 for contact of cutting wheels 432 with the sealed together films around the periphery of the package to be severed or trimmed from the advancing films.

During the downward movement of the head mechanism, ram 470 is actuated at the proper time for forcing hydraulic fluid through conduit 473 to the hydraulic motor for actuation of the latter. As explained above, actuation of the hydraulic motor causes movement of the cutting assemblies 366 in an endless horizontal path around the head mechanism. The hydraulic motor and the ram

for actuating the same are arranged so that movement is imparted to the cutting wheels just before they come into contact with the films and movement of the wheels continue for a short period of time after the wheels have separated from the severed films.

It should be apparent from the above description that the completed packages are severed at their peripheries as they are continuously advanced by the lower die plates through the cutting zone. The head mechanism is continuously reciprocated in vertical and horizontal planes in timed relation with the advancing completed packages for bringing the cutting wheels into contact with the films with the horizontal endless path defined by the cutting wheels in registry with the periphery of the packages. The cutting wheels are held in contact with the film for a sufficient length of time for the cutting wheels to sever the films around the periphery of the packages. This is accomplished by providing cam track 460 with a flattened portion. The cutting wheels of course need only move a distance in their horizontal path equal to the spacing between the cutting wheels. In actual practice, each cutting wheel moves a distance approximately equal to 1 1/4 of the spacing between the cutting wheels.

The constantly rotating cam wheels 461 lift the head mechanism from the films after a package has been severed and simultaneously move the mechanism rearwardly or upstream for continuously and successively severing completed packages being advanced in a continuous manner. During this constant reciprocation of the head mechanism, the hydraulic motor supported thereon is automatically actuated in timed relation with movement of the head mechanism to impart movement to the cutting wheels at an appropriate time for severing the films around the periphery of the package.

If for some reason rollers 388 are not engaged by a package, i.e., if by inadvertence a product was not placed on one of the loading conveyor trays thereby leaving the lower film empty over one of the lower die plates, the cutting wheels are not brought into contact with the sealed films over this one lower die plate. If rollers 388 are not engaged by a package, foot 378a of the sear is not removed from annular flange 375a on vertical rod 375. Therefore, the rod moving upwardly relative to the downwardly traveling head mechanism continues to move plate 368 upwardly as the head mechanism is being cammed downwardly. Accordingly, plates 420 are moved upwardly relative to the downwardly traveling head mechanism against the force of springs 423 by reason of the engagement of cam rollers 436 with the upper marginal portion of plate 368. When the head mechanism reaches its lowermost point of travel, the cutting surfaces of the cutting wheels are spaced a minute distance above the films (when rollers 388 are not engaged by a package). By providing cutting means 345 with rollers 388 and their related components, only filled packages are advanced beyond the cutting zone by the lower die plates.

As the cutting wheels sever a package from the films, the cutting wheels roll in an endless path on insert plate 266 of the lower die plate. The insert plates may be replaced after they have become grooved by the cutting action of the cutting wheels.

It will be apparent from FIG. 36, that engagement of rollers 388 with a package causes upward vertical movement of bar 390. Upward movement of the bar actuates counter 391 for counting packages formed by the continuous packaging machine.

Means are provided for collecting or winding scrap film which is formed after the films have been severed to separate the completed product filled packages therefrom. The scrap film is a continuous film having a plurality of longitudinally spaced-apart openings formed therein by the cutting means. As seen in FIGS. 31 through 34, the wind-up means includes a pair of vertically disposed wheels 480 spaced transversely of the machine on the cross shaft 481, which shaft has opposite ends

thereof mounted in bearing assemblies 482 and 483. Bearing assembly 482 is supported from an upright member 484 forming a part of the forming structure of the continuous packaging machine. Bearing assembly 483 is suitably mounted to one side of a housing wall 485 also forming a part of the supporting structure of the machine. The scrap film is trained under wheels 480 and then over a drum 486 which is rotatably mounted at one end thereof from housing wall 485 for rotation about an axis parallel with shaft 481. Scrap film is then wound on a wind-up cylinder 488 which is rotatably mounted at one end thereof from housing wall 485. Cylinder 488 is rotated by suitable power take-off means (not shown) from the main drive means of the continuous package forming machine.

As the lower die plates advance the separated completed packages along the downstream portion of zone 18, cam roller 298 of valve assembly 271 of each lower die plate is engaged by a lower longitudinally extending cam track 490 (FIGS. 34 and 37) having a cam face 490a. This results in opening of valve assembly 271 for communicating the vacuumized thin annular space around the periphery of ejector plunger 249 with port 285, which port is opened to atmosphere after separation of the upper and lower die plates. Accordingly, the vacuum at the underside of the lower film, i.e., at the underside of each completed package, is now broken. As the completed packages continue to travel through zone 18, cam roller 258 associated with reciprocating guide 256 is engaged by longitudinally extending cam track 259 having a forwardly and upwardly curved cam face 259a. This engagement of cam track 259 with roller 258 results in upward movement of plunger 249 from the face of the associated lower die plate.

As the completed packages are lifted in series as the lower die plates are advanced through zone 18, the completed packages are engaged at the underside of side marginal portions thereof by a pair of endless moving belts 492. Belts 492 are trained around longitudinally spaced-apart idler rollers 493 (FIG. 33) and are wound around drive rollers 494. Rollers 493 are supported by a pair of laterally spaced-apart longitudinally extending bars 495, which bars are mounted on laterally extending brackets 497 and 498. Bracket 497 is mounted from housing wall 485. Bracket 498 is mounted from a vertically extending plate 499 forming a part of the supporting structure of the machine. Rollers 494 are supported on a common cross shaft 501, which shaft is rotatably mounted at one end thereof by a bearing assembly 502 secured to the inside surface of housing wall 485. Suitable power take-off means (not shown) from the main drive means of the machine are provided for rotating shaft 501. It should be apparent that completed packages deposited on the endless traveling belts 492 are carried forwardly or downstream for deposit on suitable means, such as a conveyor assembly 503 (FIG. 31).

After the completed packages have been removed from the lower die plates by the means just described, the lower die plates returned along their lower horizontal path for continuous reuse in the package forming operation. During movement of the lower die plates along their lower horizontal path, the ejector plungers of the lower die plates are preferably returned to their seated position in the circular recesses in the lower die plates. This is accomplished by means of a cam track 505 (FIG. 15) extending longitudinally for substantially the entire length of the continuous package forming machine. Cam track 505 engages cam rollers 258 on guide assemblies 256 for retraction of the ejector plungers and for holding the same in their seated position in the lower die plates. Suitable cam track means (not shown) adapted for engagement with rollers 257 are provided at the upstream end of the machine to hold the ejector plungers in place during movement of the lower die plates between their lower horizontal path and their upper horizontal path.

While the invention has been shown in but one form it will be obvious to those skilled in the art that it is not to be so limited, but on the contrary it is susceptible of various changes and modifications without departing from the spirit and scope of the appended claims.

We claim:

1. In a machine for continuously packaging articles in separate sealed packages formed of plastic film of the type adapted to seal with itself upon contact, a supporting structure, upper and lower die plate means traveling on said structure at the same speed for advancing sheets of said film so that one film overlies the other film at a packaging zone, said upper die plate means being in communication with a source of vacuum and having means associated therewith for vacuum forming a series of depressions in said one film before the latter reaches said zone, said other film being supported by said lower die plate means so that articles to be packaged may be longitudinally spaced-apart on said other film for being covered by said depressions as the articles reach said zone, said upper and lower die plate means cooperating during their passage through said zone for forming article enclosing vacuum chambers and for physically pressing said films together between said articles to form partially completed packages unsealed at marginal portions thereof, the improvement comprising, said upper and lower die plate means having valve means operable during passage of the upper and lower die plate means through said zone for communicating said source of vacuum with the interiors of said partially completed packages via said lower die plate means and said marginal portions, one of said die plate means having vent means operable during passage of said upper and lower die plate means through said zone for communicating the exteriors of said partially completed packages to atmosphere, whereby said films are vacuum pressed into conformity with the contour of the articles and marginal portions of said films are vacuum pressed together to form completed packages.

2. In a machine for continuously packaging articles in separate sealed packages formed of plastic film of the type adapted to seal with itself upon contact, a supporting structure, upper and lower die plate means traveling on said structure at the same speed for advancing sheets of said film so that one film overlies the other film at a packaging zone, said upper die plate means being in communication with a source of vacuum, valve operated means associated with said upper die plate means for vacuum forming a series of depressions in said one film before the latter reaches said zone, said other film being supported by said lower die plate means so that articles to be packaged may be spaced-apart on said other film for being covered by said depressions as the articles reach said zone, said upper and lower die plate means cooperating during their passage through said zone for forming article enclosing vacuum chambers, said upper and lower die plate means having respective flange portions cooperating during their passage through said zone for physically pressing said films together adjacent said articles in partial package forming relation, the improvement comprising, valve operated means carried by said lower die plate means cooperating, during passage of both of said die plate means through said zone, with further valve operated means associated with said upper die plate means for vacuum pressing said films together adjacent said articles in completed package forming relation.

3. In a machine for continuously packaging articles in separate sealed packages formed of plastic film of the type adapted to seal with itself upon contact, a supporting structure, upper and lower die plate means traveling on said structure at the same speed for advancing sheets of said film so that one film closely overlies the other film at a packaging zone, the improvement comprising said upper die plate means being in communication with a source of vacuum and carrying cam operated

valve means for vacuum forming a series of depressions in said one film before the latter reaches said zone, said other film being supported by said lower die plate means so that articles to be packaged may be longitudinally spaced-apart on said other film for being covered by said depressions as the articles reach said zone, said upper and lower die plate means having respective transversely extending flange portions cooperating during their passage through said zone for physically pressing said films together adjacent said articles in partial package forming relation, cam operated valve means carried by said lower die plate means cooperating, during passage of both of said die plate means through said zone, with further cam operated valve means carried by said upper die plate means for vacuum drawing said films together adjacent said articles in completed package forming relation, and fixedly mounted cam actuating means for actuating all of said valve means in a predetermined sequence.

4. The construction according to claim 3 wherein one of said die plate means is provided with longitudinally extending fence means engageable with marginal portions of the film on the other die plate means for preventing premature sealing of marginal portions of the films during vacuumizing of said spaces.

5. In a machine for continuously packaging articles in separate sealed packages formed of plastic film of the type to seal with itself upon contact, a supporting structure, upper and lower die plate means traveling on said structure at the same speed for advancing sheets of said film so that one film closely overlies the other film at a packaging zone, said one film being wider than the other film for defining opposite overhanging marginal portions, the improvement comprising, said upper die plate means being in communication with a source of vacuum and carrying cam operated valve means for vacuum forming a series of depressions in said one film before the latter reaches said zone, said other film being supported by said lower die plate means so that articles to be packaged may be longitudinally spaced-apart on said other film for being covered by said depressions as the articles reach said zone, said upper and lower die plate means cooperating during their passage through said zone for forming article enclosing vacuum chambers, said upper and lower die plate means having respective flange portions cooperating during their passage through said zone for physically pressing said films together between said articles to form partially completed packages, cam operated valve means carried by said lower die plate means cooperating, during passage of both of said die plate means through said zone, with further cam operated valve means carried by said upper die plate means for vacuum drawing said films into conformity with the contour of the articles and vacuum drawing marginal portions of said films together to form completed packages, said lower die plate means being provided with upstanding longitudinally extending fence means adjacent opposite marginal portions of the other film engageable with said overhanging marginal portions for preventing premature sealing of marginal portions of the films, and fixedly mounted cam actuated means for actuating all of said valve means in a predetermined sequence.

6. In a machine for continuously packaging articles in separate sealed packages formed of plastic film of the type adapted to seal with itself upon contact; a supporting structure; an upper series of die plates and a lower series of die plates traveling on said structure at the same speed for advancing sheets of said film so that one film overlies the other film at a packaging zone; the improvement comprising each of said upper die plates including; a cavity and a main passageway in communication with a source of vacuum, first valve means arranged to be operated before the upper die plate reaches said zone for communicating said passageway with said cavity thereby drawing said one film into the cavity to

form a depression in the former, second valve means operable for communicating said passageway with first port means located in the face of the upper die plate outwardly of the portion thereof contacted by said one film; said other film being supported on said lower die plates so that articles to be packaged may be longitudinally spaced-apart on the other film for being received in the depressions as the articles reach said zone; said upper and lower die plates cooperating during their passage through said zone for forming article enclosing vacuum chambers; said upper and lower die plates having respective flange portions cooperating during their passage through said zone for pressing said films together between said articles to form partially completed packages; each of said lower die plates including; third valve means operable for communicating second and third port means located in the face of the lower die plate; said first and second port means registering with each other and said third port means communicating with said depressions when said upper and lower die plates form said chambers; means for operating said second and third valve means during passage of said upper and lower die plates through said zone for vacuumizing the spaces in said partially completed packages, each of said upper die plates having valve operated vent means for opening its cavity to atmosphere during said vacuumizing, whereby said films are drawn into conformity with the contour of the articles and marginal portions of said films are drawn together to form completed packages.

7. The construction according to claim 6 wherein said one film is wider than said other film for defining opposite overhanging marginal portions and wherein each of said lower die plates is provided with longitudinally extending upstanding fence means adjacent said third port means and engageable with said overhanging marginal portions to prevent premature sealing of marginal portions of the films during vacuumizing of said spaces.

8. In a machine for continuously packaging articles in separate sealed packages formed of plastic film of the type adapted to seal with itself upon contact; a supporting structure; an upper series of die plates and a lower series of die plates traveling on said structure at the same speed for advancing sheets of said film so that one film closely overlies the other film at a packaging zone; the improvement comprising, each of said upper die plates including; a cavity in the face thereof and a main passageway communicating with a source of vacuum, first cam actuated valve means operable for communicating said passageway with said cavity thereby drawing by vacuum said one film into the cavity to form a depression in the former, second cam actuated valve means operable for communicating said passageway with first port means located in the face of the upper die plate outwardly of the portion thereof contacted by said one film; first cam means fixedly mounted adjacent said upper die plates for actuating said first valve means in serial relationship before the upper die plates reach said zone; said other film being supported by said lower plates so that articles to be packages may be longitudinally spaced-apart on the other film for being received in the depressions as the articles reach said zone; said upper and lower die plates cooperating during their passage through said zone for forming article enclosing vacuum chambers; said upper and lower die plates having respective flange portions cooperating during their passage through said zone for pressing said films together between said articles to form partially completed packages; each of said lower die plates including; third cam actuated valve means operable for communicating second and third port means located in the face of the lower die plate, said first and second port means registering with each other and said third port means communicating with the depressions when said chambers are formed; first cam track means for operating said first valve means before the upper die plates reach the packaging zone and second cam track means for operating said second, third and fourth valve means during passage of said upper and lower die plates through said zone for vacuumizing the spaces in said partially completed packages thereby drawing said films into conformity with the contour of the articles and drawing marginal portions of said films together to form completed packages.

means, respectively, during passage of the upper and lower die plates through said zone for vacuumizing the spaces in said partially completed packages, each of said upper die plates having valve operated vent means for opening its cavity to atmosphere during said vacuumizing, whereby said films are drawn into conformity with the contour of the articles and marginal portions of said films are drawn together to form completed packages.

9. The construction according to claim 8 wherein each of said upper die plates includes holding means engageable with marginal portions of said one film for preventing wrinkling of the latter as it is drawn into said cavities, said holding means being in the form of a plurality of pointed members adapted to pierce marginal portions of said one film.

10. The construction according to claim 8 wherein each of said lower die plate means is provided with longitudinally extending upstanding fence means adjacent opposite margins of said other film and engageable with marginal portions of said one film for preventing premature sealing of marginal portions of the films during vacuumizing of said spaces.

11. In a machine for continuously packaging articles in separate sealed packages formed of plastic film of the type adapted to seal with itself upon contact; a supporting structure; means for advancing a sheet of said film to an upper series of die plates in substantial covering relation with the faces of the latter; means for advancing another sheet of said film to a lower series of die plates in substantial covering relation with the faces of the latter; said upper and lower die plates traveling on said structure at the same speed and in a manner so that the first mentioned film overlies the other film at a packaging zone; the improvement comprising, each of said upper die plates including; a cavity in the face thereof and a main passageway communicating with a source of vacuum, first cam actuated valve means operable for communicating said passageway with said cavity thereby drawing by vacuum said one film into the cavity to form a depression in the former, second cam actuated means operable for opening the base of said cavity to atmosphere, third cam actuated valve means for communicating said passageway with first port means located in the face of the upper die plate outwardly of the portion thereof contacted by said one film; said other film being supported by said lower die plates so that articles to be packaged may be longitudinally spaced-apart on said other film for being received in the depressions as the articles reach said zone; said upper and lower die plates cooperating during their passage through said zone for forming article enclosing vacuum chambers; said upper and lower die plates having respective flange portions cooperating during the passage through said zone for pressing said films together between said articles to form partially completed packages; each of said lower die plates including; fourth cam actuated valve means operable for communicating second and third port means located in the face of the lower die plate, said first and second port means registering with each other and said third port means communicating with the depressions when said chambers are formed; first cam track means for operating said first valve means before the upper die plates reach the packaging zone and second cam track means for operating said second, third and fourth valve means during passage of said upper and lower die plates through said zone for vacuumizing the spaces in said partially completed packages thereby drawing said films into conformity with the contour of the articles and drawing marginal portions of said films together to form completed packages.

12. In a machine for continuously packaging articles in separate sealed packages formed of plastic film of the type adapted to seal with itself upon contact, a supporting structure, upper and lower endless sets of die plates traveling on said structure at the same speed for advanc-

ing sheets of said film so that one film overlies the other film at a packaging zone, valve operated means associated with said upper die plates for forming a series of depressions in said one film before the latter reaches said zone, said other film being supported by said lower die plates for being advanced in a horizontal plane, means for successively depositing articles to be packaged on said other film in longitudinal spaced-apart relation for being covered by said depressions as the articles reach said zone, said upper and lower die plates cooperating during their passage through said zone for forming article enclosing vacuum chambers; said upper and lower die plates having respective flange portions cooperating during their passage through said zone for pressing said films together adjacent said articles in partial package forming relation, valve operated means carried by said lower die plates cooperating, during passage of both of said die plate means through said zone, with further valve operated means associated with upper die plates for drawing said films together in completed package forming relation, only one of said sets of die plates being connected with a source of vacuum and means for separating the completed packages from said films as the latter are being advanced from said zone.

13. In a machine for continuously packaging articles in separate sealed packages formed of plastic film of the type adapted to seal with itself upon contact, a supporting structure, upper and lower die plate means traveling on said structure at the same speed for advancing sheets of said film so that one film closely overlies the other film at a packaging zone, said upper die plate means being in communication with a source of vacuum and carrying valve operated means for vacuum forming a series of depressions in said one film before the latter reaches said zone, said other film being supported on said lower die plate means for being advanced in a horizontal plane, means for successively depositing articles to be packaged on said other film in longitudinal spaced-apart relation for being covered by said depressions as the articles reach said zone, said upper and lower die plate means cooperating during their passage through said zone for forming article enclosing vacuum chambers; said upper and lower die plate means having respective flange portions cooperating during their passage through said zone for pressing said films together adjacent said articles in partial package forming relation, valve operated means carried by said lower die plate means cooperating, during passage of both of said die plate means through said zone, with further valve operated means carried by said upper die plate means for drawing by vacuum said films together in completed package forming relation, the upper die plate means only being in communication with the source of vacuum and means for separating the completed packages from said films as the latter are being advanced from said zone.

14. In a machine for continuously packaging articles in separate sealed packages formed of plastic film of the type adapted to seal with itself upon contact, a supporting structure, upper and lower die plate means traveling on said structure at the same speed for advancing sheets of said film so that one film overlies the other film at a packaging zone, said lower die plate means supporting said other film in a generally horizontal plane so that articles to be packaged may be carried on the former in longitudinal spaced-apart relation, the improvement comprising, said upper and lower die plate means each including first and second means for physically pressing and vacuum drawing, respectively, said films together around the articles as the upper and lower die plate means pass through said zone thereby forming separate sealed packages, said second means including cam actuated valve means, said lower die plate means being adapted to advance the sealed together films to a cutting zone which includes overhead mounted cutting means for severing the films thereby disconnecting the packages from each

other, which lower die plate means includes further cam actuated valve means which cooperate with said second means of the lower die plate means for temporarily holding said other film on the lower die plate means until the films have been severed.

15. In a machine for continuously packaging articles in separate sealed packages formed of plastic film of the type adapted to seal with itself upon contact, a supporting structure, and upper endless series of die plates and a lower endless series of die plates traveling on said structure at the same speed for advancing sheets of said film so that one film overlies the other film at a packaging zone, each of said lower die plates including a substantially planar die face and said lower die plates being adapted for supporting said other film on said faces in a generally horizontal plane so that articles to be packaged may be carried on said other film in longitudinal spaced-apart relation, said upper die plates being in communication with a source of vacuum, said upper and lower die plates including first and second means for physically pressing and vacuum drawing, respectively, said films together around the articles as the upper and lower die plates pass through said zone whereby forming separate sealed packages, the improvement comprising, said second means including cam actuated valve means on each of the upper die plates and cooperating with separate cam actuated valve means on each of the lower die plate means for communicating said source of vacuum with the lower die plates to vacuum draw said films together by means of ports in the upper and lower die plates, each of said lower die plates including further means operable in part by said second means for temporarily holding said other film on its face after passage of the films through said zone, said further means including additional cam actuated valve means on each of the lower die plates for communicating said source of vacuum with the underside of said other film.

16. The construction according to claim 15 wherein separate linear cam track means mounted in said zone adjacent said upper and lower die plates parallel with the path of movement of the latter along said plane are engageable with all of said valve means, respectively, for actuating the same in a predetermined sequence.

17. In a machine for continuously packaging articles in separate sealed packages formed of plastic film of the type adapted to seal with itself upon contact, a supporting structure, an upper endless series of die plates and a lower endless series of die plates traveling on said structure at the same speed for advancing sheets of said film so that one film overlies the other film at a packaging zone, the improvement comprising, each of said upper die plates including a main passageway in communication with a source of vacuum and valve means operable for communicating said passageway with first port means located in the face of the upper die plate outwardly of the portion thereof contacted by said one film, said other film being supported on said lower die plates in a generally horizontal plane so that articles to be packaged may be longitudinally spaced-apart on the other film, each of said lower die plates including valve means operable for communicating second port means located in the face of the lower die plate outwardly of the portion thereof contacted by said other film with third port means located in the face of the lower die plates in the portion thereof contacted by said other film, said first and second port means being in registry during passage of the upper and lower die plates through said zone, said upper and lower die plates cooperating during their passage through said zone for pressing and drawing said films together around said articles to form separate completed packages, said lower die plate means being adapted to advance the sealed together films to a cutting zone which includes overhead mounted cutting means for severing the films thereby disconnecting the packages from each other, and means for actuating the valve means of the upper and lower die plates during

their passage through said zone for communicating said source of vacuum with the underside of said other film to hold the latter to the lower die plates, the valve means of the lower die plate means being adapted to maintain the vacuum at the underside of said other film until the films have been severed.

18. The construction according to claim 17 wherein further means are provided for actuating the valve means of the lower die plates after their passage through said cutting zone for communicating the underside of said other film to atmosphere through said second port means thereby releasing the other film on the lower die plates.

19. In a machine for continuously packaging articles in separate sealed packages formed of plastic film of the type adapted to seal with itself upon contact; a supporting structure; an upper endless series of die plates and a lower endless series of die plates traveling on said structure at the same speed for advancing sheets of said film so that one film overlies the other film at a packaging zone; the improvement comprising, each of said upper die plates including a main passageway in communication with a source of vacuum and valve means operable for communicating said passageway with first port means located in the face of the upper die plate outwardly of the portion thereof contacted by said one film; said other film being supported on the lower die plates in a generally horizontal plane so that articles to be packaged may be longitudinally spaced-apart on the other film; each of said lower die plates including; a substantially planar face having a centrally disposed recess, an ejector plunger mounted in said recess for reciprocation in a direction normal to said face and having the upper surface thereof co-planar with said face when the ejector is seated in the recess, the periphery of said plunger defining with the periphery of said recess, when the plunger is seated in the recess, a thin annular space in communication with the base of the recess, valve means operable for communicating second port means located in the face of the lower die plate outwardly of the portion thereof contacted by said other film with third port means located in the base of said recess; said first and second port means being in registry during passage of the upper and lower die plates through said zone; said upper and lower die plates cooperating during their passage through said zone for pressing and drawing said films together around said articles to form separate completed packages; and means for actuating the valve means of the upper and lower die plates during their passage through said zone for communicating said source of vacuum with the underside of said other film at the thin annular spaces to hold the other film to the lower die plates; said lower die plates being adapted to advance the sealed together films to a cutting zone which includes overhead mounted cutting means for severing the films thereby disconnecting the packages from each other; the valve means of the lower die plates being adapted to maintain the vacuum at the underside of said other film until after passage of the films through said cutting zone.

20. The construction according to claim 19 wherein further means are provided for actuating the valve means of the lower die plates after their passage through said cutting zone for communicating the underside of said other film to atmosphere through said second port means thereby releasing the other film on the lower die plates.

21. The construction according to claim 19 further defined by, each plunger including a stem extending through an opening in the corresponding lower die plate and being provided with roller means of the free end thereof, cam track means engageable with said roller means after passage of the lower die plates through said cutting zone for successively ejecting said plungers upwardly from the faces of the lower die plates for transfer of packages resting on the plungers to delivery conveyor means.
22. In a machine for continuously packaging articles in separate sealed packages formed of plastic film of the type adapted to seal with itself upon contact, a supporting structure, an upper endless series of die plates and a lower endless series of die plates traveling on said structure at the same speed for advancing sheets of said film so that one film overlies the other film at a packaging zone, the improvement comprising, each of said upper die plates including a main passageway in communication with a source of vacuum and valve means operable for communicating said passageway with first port means located in face of the upper die plate outwardly of the portion thereof contacted by said one film, said other film being supported on said lower die plates in a generally horizontal plane so that articles to be packaged may be longitudinally spaced-apart on the other film, each of said lower die plates including valve means operable for communicating second port means located in the face of the lower die plate outwardly of the portion thereof contacted by said other film with third port means located in the face of the lower die plate in the portion thereof contacted by said other film, said first and second port means being in registry during passage of the upper and lower die plates through said zone, said upper and lower die plates cooperating during their passage through said zone for pressing and drawing said films together around said articles to form separate completed packages, and means for actuating the valve means of the upper and lower die plates during their passage through said zone for communicating said source of vacuum with the underside of said other film to hold the latter to the lower die plates, said lower die plates being adapted to advance the sealed together films to a cutting zone which includes overhead mounted cutting means for severing said films around the periphery of the packages thereby separating the packages from the films and forming scrap film, overhead roller means mounted adjacent said cutting zone for removing scrap film from the lower die plates, the valve means of the lower die plates being adapted to maintain the vacuum at the underside of said other film until after the scrap film has been removed from the lower die plates.
